COIL WINDING MACHINE

James S. Burge and Otis K. Gray, Anderson, Ind.,
assignors to General Motors Corporation, De-
troit, Mich., a corporation of Delaware

Application September 9, 1939, Serial No. 294,130

56 Claims. (Cl. 242—10)

This invention relates to the manufacture of electrical coils and more particularly to the manufacture of induction coils having primary and secondary windings.

Heretofore it has been the practice in the manufacture of ignition coils, particularly for automobile use, to wind a plurality of secondary windings on the same arbor, then separate these windings and assemble them with individually wound primary windings. It is an object of the present invention to provide for the winding of primary windings simultaneously around a plurality of secondary windings which remain on the arbor upon which the secondary windings were wound.

In connection with the winding of a plurality of primary windings simultaneously around a plurality of secondary windings on a single arbor, it is a further object of the invention to provide means independent of the secondary windings for anchoring the starting leads of the primary windings to the winding arbor. In the disclosed embodiment of this invention, we provide this anchoring means through the use of a strip of tough, flexible, insulating material, the ends of which are anchored to the head stock and tail stock spindles with which the arbor is connected, said strip being provided with apertures for the reception of the starting leads of the primary winding. This strip will not bend laterally away from the axis of the arbor yet it is sufficiently flexible to be wrapped around the arbor as the primary windings are wound around the arbor.

When winding a plurality of secondary coils, which are of fine wire, upon the same arbor, it has been the practice to wind over each layer of winding a single strip of insulating paper having a width equal to the sum of the widths of the separate secondary coil units. After all of the layers of paper have been wound upon the arbor, then the paper is slit at points between the sections of secondary winding in order to separate the windings. Such is the status of the assembly of the arbor and secondary windings when it is placed upon the machine of our present invention. Instead of using a single wide strip to insulate the turns of the primary windings wound upon the arbor by our present machine, we prefer to use individual paper insulating strips for each primary coil. It is, therefore, a further object of the present invention to provide a mechanism under the control of the operator and operated by power of the machine for simultaneously feed-

ing strips of insulating paper to the several primary coil windings.

At the end of the winding operation performed by our new machine, the primary coils will be joined together only by the insulating strip referred to above. It is, therefore, a further object of the invention to provide means for severing the insulating strip before the arbor and windings thereon are removed from the machine.

A further object of the invention is to provide an improved turn counter and adjustable means for signaling to the operator when a certain number of turns are wound on each layer.

A further object of the invention is to provide for the facile anchoring of the primary wire to the wire guides at the time these wires are severed from the primary windings on the arbor.

A further object is to provide for the abrupt lateral movement of the wire guides automatically in response to the reversal of the mechanism actuated by feed screws for moving wire guides in order that the ends of the layers of wire will be relatively off-set.

A further object is to provide means for locking the wire guides against accidental lateral movement.

A further object is to provide for the facile removal and replacement of the wire unreeeling spindle.

A further object is to support the wire spools in such manner that loops of wire therefrom will not become lodged under the spools in such manner as to interfere with the proper unreeeling of the wire.

A further object is to provide for the transmission of power to the winding arbor through a friction clutch controlled in such manner that the torque transmitted by it will vary in accordance with the pressure exerted upon a foot pedal.

Further objects and advantages of the present invention will be apparent from the following description, reference being had to the accompanying drawings wherein a preferred embodiment of the present invention is clearly shown.

In the drawings:

Figs. 1 to 1E inclusive, are perspective diagrammatic views showing various steps in the winding operation. Fig. 1 shows the arbor with a plurality of secondary windings thereon. Fig. 1A shows the application of the insulating anchoring strip. Fig. 1B shows the application of the start leads of the primary wires to the insulating strip. Fig. 1C shows the application of resilient metal clamps of insulating strip to bend it around the secondary windings before winding

by the power of the machine. Fig. 1D shows the first layer of the primary turns wound around the insulating strip. Fig. 1E shows the starting of the several strips of insulating paper to be wound in between successive layers of primary windings.

Fig. 2 is a fragmentary perspective view showing the completion of the application of a sheet of insulating paper to one of the coils on the arbor when starting to wind the second layer of wire turns on the coil.

Fig. 3 is a fragmentary perspective view of one of the coil sections at the end of the winding of the second layer of turns.

Fig. 4 is a fragmentary perspective view showing, during the winding of the last layer of turns, the operation of the winding in a loop of cloth tape to serve as means for anchoring the end turn of the coil.

Fig. 5 is a view similar to Fig. 4 showing that the end turn of the end lead of the coil has been inserted in the loop of cloth tape and the loop drawn tight to secure it and the end lead in operative position.

Fig. 6A is a diagrammatic perspective view of a coil section showing the relative location of the start and end leads of the primary coil and the outside end lead of the secondary coil.

Fig. 6B is a view similar to Fig. 6A showing the attachment of the outside end lead of the secondary coil to the inside end lead of the primary coil and the relative location of this connection to the outside lead of the primary coil.

Fig. 7 is a perspective view of the entire machine for carrying out the operations of Figs. 1A through 5.

Fig. 43 is a diagram of certain controls of the winding head, the fragmentary parts being taken substantially on the line 43-43 of Fig. 33.

Fig. 44 is a fragmentary sectional view of a portion of the apparatus shown in Fig. 43.

Fig. 45 is a fragmentary plan view of the lever 360 looking in the direction of arrow 45 of Fig. 43.

Fig. 46 is a fragmentary view looking in the direction of the arrow 46 of Fig. 43.

Fig. 49 is a diagrammatic view of the controls of the machine showing the status of these controls when paper is being fed to the winding arbor.

Fig. 50 is a fragmentary sectional view of support 183 shown in Fig. 49.

Fig. 47 is a view of the controls showing the status of the elements when the knife is being operated to sever the insulating strip.

Fig. 48 is a fragmentary sectional view of bracket 609 shown in Fig. 47.

Fig. 51 is a diagrammatic view of the mechanism for controlling the paper supply unit C and the fingers F, the paper supply unit C being located in an intermediate position in which it is disconnected from the power driving mechanism,

the fingers F being located in a position in which they bear upon the paper strips being wound upon the arbor.

Fig. 52 is a fragmentary view showing a bracket for supporting a part of the mechanism shown in Fig. 51.

Fig. 53 is a view similar to Fig. 51, the fingers F being fully retracted while the paper supply unit C remains in the position shown in Fig. 51.

Fig. 54 is a view looking in the direction of arrow 54 of Fig. 55.

Fig. 55 is a sectional view taken on the line 55—55 of Fig. 54.

Fig. 56 is a sectional view taken on the line 56—56 of Fig. 55.

Referring to Figs. 1 to 1E, particularly Fig. 1, numeral 60 designates an arbor upon which has been wound a plurality of secondary windings 61 comprising layers of wire turns separated by turns of a strip of paper. The paper strip originally had a width equal to the sum of the widths of the individual winding sections. After winding the secondary turns, the paper strip is slit at 61X, in order that the winding sections will be separated before they are removed from the arbor 60. The arbor 60 with the winding 61 upon which they were originally wound is placed in the machine of the present invention. Without going further into the description of the present machine, it will be sufficient to state with respect to the explanation of Fig. 1 that the machine has a winding head or stock D and a tail stock E. The arbor driving member D1 of the head stock, shown diagrammatically in section in Fig. 1, is provided with a central hole for receiving one end of the arbor 60 which is provided with a slot 62 for receiving a cross pin 63 carried by the member D1. The other end of the arbor 60 is supported in a similar manner by the rotatable tail stock element E1, and the arbor 60 is drivingly connected with E1 by a similar pin and slot connection. The elements D1 and E1 are provided with pins 64 and 65 respectively. These pins are arranged in groups of three. The center one of each group is radially disposed relative to the axis of the arbor 60 and the other pins of each group are parallel to the center pin. The pins 64 carried by element D1 are arranged in diametrically opposite groups of three pins each. The same is true with respect to the pins 65 carried by element E1. The pins 64 and 65 are round or circular in cross section. In addition to the pins 64, the element D1 is provided with two diametrically opposite hook-like pins 64a. Likewise element E1 carries diametrically opposite hook-like pins 65a. The width of the pins 64a and 65a measured along a line parallel of the axis of the arbor 60 is substantially twice the diameter of the pins 64 or 65.

The arbor 60, with the secondary winding 61 carried thereby is mounted upon the head stock member D1 and the tail stock member E1 is drivingly connected with these members. The notches 62 provided at the opposite ends of the arbor 60 are in alignment. The cross pin 63 of head stock member D1 bears a relation to the pins 64 and 64a thereof which is the same as the relation which a similar pin 63 carried by tail stock member E1 bears to its pins 65 and 65a. Therefore, when the arbor 60 is properly mounted upon the member D1 and E1 the pins 64 of D1 will be longitudinally aligned with pins 65 of E1 and the hook-like pin 64a of D1 will be longitudinally aligned with hook-like pins 65a of E1, as shown in Fig. 1.

The next step is to mount upon the members D1 and E1 an anchoring strip 70 of insulating material which is tough and strong, yet flexible. Near its left-hand end, the strip 70 is provided with three round holes 74 for receiving a group of the pins 64 and with an elongated hole 74a for receiving the hook pin 64a of member D1. Near its right-hand end the strip 70 is provided with three round holes 75 for receiving a group of pins 65 of element E1 and with an elongated hole 75a for receiving the hook pin 65a of E1. The pins 64 of D1 and the pins 65 of E1 are received by the holes 74 and 75 of strip 70 while the strip 70 is still in the flat condition, as shown in Fig. 1A. As the strip 70 is caused to be wrapped around the arbor 60 as indicated in Fig. 1C, the holes 74a and 75a are caused, respectively, to receive the hook pins 64a and 65a of elements D1 and E1, respectively, as shown in Fig. 1A. The hooks 64a and 65a are so curved with respect to the pins 64 and 65 that, as the strip 70 is formed cylindrically about the windings on the arbor 60, the side walls of the holes 74a and 75a of the strip 70 will follow the shape of the hook 64a and 65a. The purpose of the connection between the strip 70 and the hooks 64a and 65a is to provide means in addition to the pins 64 and 65 for drivingly connecting the strip 70 with the parts D1 and E1. The pins 64a and 65a are made wider, longitudinally of the arbor 60 than the diameter of the pins 64 and 65 in order to minimize the tendency for the insulating strip 70 to tear out around the pins 64 and 65 and the hooks 64a and 65a.

The anchoring strip 70 is provided at its front edge with spaced notches 71 and near its middle with spaced round holes 72 and with spaced L-shaped holes 73 which somewhat resemble bayonet slots. It is apparent that in the same plane at right angles to the axis of the arbor 60 there will be located a notch 71 and a hole 72 and, a little to the left of that plane, will be located an L-shaped hole 73. All of these holes 72 and 73 and notches 71 bear a definite relation to the holes 74 and 75 which receive the pins 64 and 65 of element D1 and D2. Pins 64 and 65 bear a definite relation to the cross slot 62 in the ends of arbor 60. The secondary windings 61 which were previously wound on the arbor 60 have end leads which bear a definite relation to the end slots 62 in the ends of arbor 60. We are particularly interested in the location of the outside end lead of each of the windings 61. This end lead is a short length of flexible wire (fastened to an end of the fine wire secondary coil) which is buried under a few layers of paper wrappings and can easily be felt by pressing a finger against any of the secondary windings 61. Since the cross slots 62 in arbor 60 are diametrically disposed, it is apparent that there are two possible ways in which the arbor may be located with respect to the parts D1 and D2. Hence there are two possible ways in which the concealed end leads of the secondary windings 61 can be located with respect to the operator who stands in front of the machine ready to mount the insulating anchoring strip 70. Therefore, since there is only one proper location of the end leads of the secondary windings relative to the strip 70, the operator must know where the concealed end leads of the secondary windings are located; and he can tell this either by feeling for it or by observing a designating mark previously placed upon the winding 61 to denote the location of these concealed secondary end leads. The proper lo-

cation of the strip 70 is such that the L-openings 73 will be located adjacent these concealed secondary leads. Therefore the operator must rotate the arbor so that these concealed leads will be located above the axis of arbor 60 and back of the vertical plane passing thru its axis.

The starting ends of primary wires W are passed thru the holes 72 as indicated at W1, then under the strip 70 and forwardly as indicated at W2 and then bent back to provide hooks indicated at W3 received by the notches 71. In this way the starting ends of the primary wires W are anchored to the strip 70 and are thus anchored to the power driving means of the machine independently of the secondary coils 61 mounted upon the arbor 60. This feature is of great importance when one considers that the secondary windings comprise layers of turns of relatively fine wire and the paper layers are formed from relatively thin paper. When winding upon these relatively fragile materials a relatively coarse primary wire which should be tightly wound, it is essential that the winding of the primary wire be handled in such a way as not to disturb nor mar the insulation of the secondary windings or disrupt them entirely. Therefore we believe that an advance has been made in this art by the provision of the anchoring and driving strip 70 by means of which the starting ends of the primary wires W are drivingly connected with the power drive of the machine (including elements D1 and E1) independently of the secondary windings 61 previously wound upon the arbor.

The next step, shown in Fig. 1C, is to cause the anchoring strip 70 to be formed around the secondary winding 61. This is accomplished by forcing a plurality of spring clips 76 into position around the arbor thereby causing the anchoring strip 70 to take a cylindrical form. The clips 76 are made of light weight spring steel and are sufficiently resilient to be readily mounted in position and removed from the position shown in Fig. 1C. Yet the clips 76 must provide sufficient tension to form the strip 70 into cylindrical formation. When strip 70 is shaped into cylindrical formation, it becomes a tube anchored at both ends to means driven by the machine; and, being in the form of a tube, it is sufficiently strong to transmit to the wires W the force necessary to unreel these wires from supply spools and to draw the wires thru tension devices, without the strip being bent or torn from its moorings provided by the elements D1 and E1. While the clips 76 remain mounted upon the strip 70, as shown in Fig. 1C, the arbor 60 is rotated counterclockwise, as indicated by arrow 77 in Fig. 1C, to cause a few turns of wire to be wound upon the arbor so that strip 70 will be retained in cylindrical formation without requiring further use of the clips 76. The clips 76 are then removed and the winding is continued in order to complete the winding of the first layer L1 of wire, as shown in Fig. 1D.

Individual strips of paper P are fed from a paper supply means in such manner that the leading ends of the strips are caused to be located between the windings L1 and resilient metal blades or fingers F which, at the beginning of the application of paper strips P to the windings, as shown in Fig. 1E, are located in a position above and spaced from the layers L1, but in such position as to cause the leading ends of the strips P to be moved between the layers L1 and the wires W leading to these layers. In this way the leading ends of the paper strips P will be

gripped between the wires W and the material already wound upon the arbor. Therefore, when the arbor 60 is rotated counterclockwise as viewed from the left of Fig. 1E, the paper strips P will be wound around the layers L1. This operation is performed when starting to wind the second layer. After the ends of the paper strips have been caught between the wires W and the layers L1 so that the strip P may be withdrawn from supply stacks of paper strips by the rotation of the arbor 60, the fingers F are retracted from the position shown in Fig. 1E to that shown in Fig. 2. In the position shown in Fig. 2 the fingers are held against the paper strips P being wound upon the layers L1 so as to cause the strips P to be formed smoothly in cylindrical shape around the layers L1 without wrinkles or bulges. After a few turns of the second layer of wire indicated at L2 in Fig. 2, have been wound, the fingers F are retracted so as to permit the completion of the winding without interference from the fingers F. The completion of the second layer L2 is indicated in Fig. 3.

The direction of wire guide feed is then reversed and the third layer is wound. At the end of the winding of the third layer the direction of feed of the wire guides is reversed so that the winding of the fourth layer may take place. The fourth layer is designated L4 in Figs. 4 and 5. During the winding of the fourth layer a loop of cloth insulation 71 is applied before the winding is completed. At the completion of the winding of L4 the end lead 78 is severed from the wire leading from the supply reel and wire tension device of the machine. The end lead 78 is passed thru the loop 71 and then this loop is drawn tight (see Fig. 5) so that the end lead 78 will be securely anchored.

The loop 71 must be so placed that it will be diametrically opposite the L-shaped holes 73 of the strip 71. These L-holes 73 are always visible since the windings do not cover these holes. After all of the end leads 78 of the plurality of coils being wound have been anchored in the manner shown in Fig. 5 and have been severed from their respective supply wires, a plurality of cutter blades are applied simultaneously to the arbor while it is rotating in order to cut the strip 70 along lines which are indicated by dot-dash lines 79 in Fig. 1B. These cutting lines all pass thru the left-hand ends of L-holes 73 so that each completed coil section will include, as shown in Fig. 6A, a secondary winding 61, a section of drive strip 70 and layers L1, L2, L3 and L4 of primary winding separated by paper strips P1, P2 and P3. In Fig. 6A we do not attempt to show the section as actually made but have purposely displaced axially the various layers of windings and paper insulators, in order to show more clearly the relation of the end leads of the primary and secondary windings. In Fig. 6A 61a designates the concealed outside end lead of the secondary winding 61. As stated before, the anchor strip 70 was so mounted upon elements D1 and E1 and relative to the arbor that the concealed end leads 61a would come adjacent to the L-Holes 73. Therefore, the individual coil sections provided after severing the anchoring strip 70 along lines 79 will each be provided with what appears as a bayonet slot 73x in Fig. 6A. The secondary end lead 61a is withdrawn from its hiding place and is passed into the bayonet slot 73x. Likewise the start lead L1S of layer L1 is unhooked from the notch 71 and it is passed into slot 73x and then both leads 61a and L1S

are pulled into the anchoring end of slot 73x and are twisted together and electrically united by soldering, the insulating enamel on L1S having previously been scraped off. As shown in Fig. 6B the united wires 61a and L1S are located diametrically opposite the primary end lead 78. This arrangement is required particularly for use with an ignition coil having primary terminals located at the same end of the coil case and diametrically opposite sides of a central high tension terminal with which the inside lead of the secondary coil 61 is connected.

It will be understood that means are provided for retracting the tail stock element E1 from the head stock element D1 so that the arbor 60 and its windings may be removed and the arbor be withdrawn from the separated coil units.

In order that the operator may know when to stop winding any layer of primary windings, the machine is provided with a suitable turn counter and electric lamp indicator to be described later.

Referring to Fig. 7, the machine comprises chiefly a wire supply unit A which supports wire supply spools and wire unreeling devices, a wire guide unit B which is shifted longitudinally during the winding so that layers of wire will be evenly wound upon the arbor. The unit B includes means for anchoring the free ends of the wires leading from the supply spools. The letter C refers to the paper supply units from which strips of paper P are simultaneously removed and applied to the arbor as shown in Fig. 1E. The letter D refers to the gear box and head stock unit which drives the member D1, shown in Figs. 1 to 1E. The letter E indicates the tail stock unit which includes element E1. Associated with the tail stock unit E is an indicator return lever IR which returns to zero position the indicator or turn counter mechanism I mounted upon the gear box unit D. Near the lever IR is located the guide return lever GR which returns to start position the wire guide and wire anchoring unit B. In front of and below the head stock unit D is located a guide control lever GC which shifts a screw-fed nut from one screw to another in order to cause the wire guide assembly B to be moved either to the right or to the left with respect to the arbor during the winding operation. To the right of the head stock unit D is located a handwheel H by which the arbor may be turned manually.

All of these units are supported by a table 80 which is supported above the floor by pedestals or legs 81 and 82. An electric motor M is supported by the leg 81 and by an auxiliary bracket 83 fastened to the table 80. Below the table 80 are located three control pedals. One of these is pedal T, which controls the application of power from the motor M to the winding arbor. Pedal T is in the nature of a throttle pedal since it is used to control a hydraulic means which in turn controls the application of power from an electric motor driven shaft to the gearing in the unit D through a friction clutch which is so constructed as to slip more or less according to whether the operator applies a light or heavy pressure upon the pedal T. To the right of pedal T is a knife controlling pedal KC and to the right of pedal KC is a paper supply controlling pedal PC. 70

Wire supply unit A

Referring to Figs. 7, 8 and 10 to 14A, the unit A comprises side brackets 90 and 91 supported by the table 80 and supporting shelves 92, 93 and 75

94. Shelves 92 and 93 each support a plurality of spools, S, generally made of wood. Referring particularly to Fig. 11, each shelf is provided with sleeves 95 of such outside diameter as to loosely receive the hub of spool S. The spool is held from turning by a plurality of pointed studs 96 supported by the shelf and grouped around the sleeve 95. The weight of the spool and the wire carried thereon is sufficient to cause the spool to rest upon the points of the stud 96 which extends into the wooden flanges of the spool. The studs 96 are located in a circular row of such diameter that these studs are practically flush with the periphery of the lower flange of the spool S. The number of studs 96 is sufficient to enable the circular row of studs to act as a barrier to prevent interference with the unreeling of any loose coil of wire which might drop from a full wire spool below the lower flange of the spool at the time the wire is being unreeled. Such an accidentally dislodged loop of wire would contact with the studs 96 and thus be prevented from becoming untangled around the sleeve 95 around which the spool S is placed.

Each sleeve 95 supports an unreeling spindle 97 having a reduced portion 98 extending through the spindle and below its lower end where this portion is provided with an annular groove 99 adapted to receive a forked bar 100 attached to a rod 101 guided by a plate 102 secured to the shelf (93 or 92) which supports the sleeve 95. The forked bar 100 slides in a straight notch 103 provided by a bushing 104 secured to the shelf. A spring 105 is located between the bar 102 and a shoulder 106 provided by the rod 101. That portion of rod 101 which projects beyond the outside or the right of the plate 102 is bent over to provide a handle 107. Before the spindle 97 can be removed from the sleeve 95 in order to replace a spool S, the operator must withdraw the bar 100 from engagement with the lower end of the spindle 98 by pulling out on the handle 107. As shown in Fig. 13A, that portion of spindle 97 which defines the bottom of the groove 99 is provided with flats 99a diametrically opposed and spaced apart at a distance slightly less than the distance between the tines of the fork 100. When fork 100 is located as shown in Fig. 13A, the tines of fork 100 are not only received by the groove 99 but they are also located so as to embrace the flats 99a and thus prevent rotation of spindle 97 as well as axial movement thereof. When the operator replaces an empty spool with a full one which is placed upon the sleeve 95 and upon the pointed studs 96, the operator then replaces the spindle 97 by dropping it through the sleeve 95. It will drop sufficiently to locate the groove 99 in a horizontal alignment with the fork bar 100, but it will frequently happen that the flats 99a are not in alignment with the notch of the forked bar 100. Under these conditions, when the operator releases the handle 107 which he has held while dropping the spindle 97 into position, the bar 100 will snap into the groove 99 as shown in Fig. 13B. The tines of the bar 100 will engage the spindle and will prevent the axial movement thereof but will permit it to be turned in order to align the flats 99a with the notch of the bar 100. When this occurs, the bar 100 will snap into position shown in 13A due to the action of spring 105. It is not necessary for the operator to rotate the spindle 97 in order to align the flats 99a of spindle 97 with the notch of bar 100 since the spindle 97 is frictionally dragged rotatively

by the unreeling device which will now be described.

At its upper end spindle 97 carries a ball bearing 110, the outer race of which supports a hub 111, carrying an unreeling arm 112, supporting an unreeling pulley 113. The hub 111 encloses a brake provided by a friction disc 114 interposed between hub 111 and disc 115 having a flat 116 engaging a corresponding flat provided by spindle 97 as shown in Fig. 12. Disc 115 is non-rotative. The amount of frictional resistance to the rotation of hub 111 is controlled by the compression of a spring 117, the compression of which is adjusted by nuts 118 and 119 threaded upon the upper end of the spindle 97. The friction disc 114 may be made of oil absorbing felt into which lubricant may be fed from a tiny reservoir provided within the circumference of a flange 115a provided by disc 115. The disc is provided with small holes 115b through which oil passes into the disc 114. From the disc 114, oil may pass through holes 111a to the ball bearing 110.

As shown in Fig. 14, the wires W are led over the supply spools S and passed around the unreeling pulleys 113 and then upwardly around guide pulleys 120 supported by brackets 121 which are carried in part by the shelf 93 and others by the shelf 94.

Wire guiding and anchoring assembly B

The wire guiding assembly B comprises a plurality of wire guiding and anchoring units 125 which are provided with a hub 126 apertured to receive a tube 127 which is supported for horizontal, longitudinal movement by the machine and which is moved parallel to the winding arbor in either direction by means of a feed nut which cooperates with feed screws in a manner to be described. The hub 126 is clamped to the tube 127 by means of a screw 128 passing through a sleeve 129 and threaded into a nut 130. The parts 129 and 130 are received by a circular aperture in the hub 126 and are provided with cylindrical portions 131 and 132, respectively, which conform to the shape of the tube 127. The head of the screw 128 bears against the sleeve 129. When the screw is turned in one direction the members 129 and 130 will be forced against the tube 127 thereby securing the unit 125 to the tube in the proper position.

As viewed in Fig. 16, the wire W moves in the direction of right toward left as indicated by arrows 133 and 134. Referring to Figs. 20 and 16, the wire first passes between pulley 135 and a hinged block 136. Pulley 135 is mounted on a stud 137 carried by a plate 138 adjustably secured to the bracket 125. The block 136 is hinged by a pin 139 carried by a bracket 140 attached to the plate 138. A helical coil spring 141 surrounding pin 139 urges the block 136 in a counterclockwise direction into the position shown in Fig. 20 thereby confining the wire W within the groove of the pulley 135. The block 136 can be moved clockwise by a handle 142 attached thereto.

The wire next passes around a pulley 150 shown in section in Fig. 21. Pulley 150 is supported on a rod 151 having a shoulder 152 providing a pivot bearing for the plate 138. The rod 151 is provided with a threaded shank 153 extending through the bracket 125 and receiving a nut 154 which clamps the rod 151 to the bracket 125. The plate 138 is adjustably secured in a certain position of its rotation around the pin 151

by means of a bolt 155 extending through an arcuate slot 156 the center of curvature of which is the axis of the rod 151. The bolt 155 extends through a plain hole in bracket 125 and receives a nut 157, the tightening of which clamps causes the plate 138 to be clamped to the bracket 125 in the desired position of adjustment.

Referring to Fig. 19 as well as Fig. 16, the wire W next passes between a pulley 160 and a retaining block 161. The pulley 160 is mounted on a reduced end of a screw stud 162, the shoulder of which bears against the bracket 125 and is there retained by tightening of a nut 163 which engages threaded shank 164 of the stud 162. The block 161 is pivoted on a hinged pin 165 carried by a bracket 166 secured to the bracket 125 by screws 167. A helical coil spring 168 is supported by the pin 165 and is so biased as to urge the block 161 into wire retaining position, as shown in Fig. 19. The block 161 is provided with a handle 169 by which it may be turned counterclockwise.

The wire W finally passes around a grooved pulley 171, see Figs. 18 and 16, journaled on a ball bearing 172 supported by a screw stud 173 which clamps the inner race of the bearing to the bracket 125. The wire is guided into the groove of the pulley 171 by a flange 174 provided by the bracket 125 and by flange 175 provided by a bracket 176 secured to the bracket 125 by screws 177.

The hub 126 of each bracket 125 carries a roller 180 secured thereon by screw stud 181. The rollers 180 of the various brackets 125 are supported by an inclined plate or rail 182 (see Figs. 8, 10 and 49) which is carried by a plurality of brackets 183 supported by table 80. One bracket 183 is shown in Figs. 49 and 50. A left-hand end bracket 183 is shown in Fig. 8, and a right-hand end one is shown in Fig. 10. In this way the weight of tube 127 and the various units B, including the brackets 125 and parts carried thereon, are transmitted through to the rollers 180 to the rails 182 and through brackets 183 to the table 80.

The wire guide unit 125 is not only a means for guiding a wire while it is being wound upon the arbor, but the unit 125 provides also means for keeping the wire taut between the unit 125 and the arbor. Referring to Fig. 16 it will be noted that the wire W passes in succession around the pulleys 135, 150 and 160 thereby placing a kink in the wire. On account of this kink, that portion of the wire between the unit 125 and the arbor is under tension, while that portion between the unit 125 and the unreeling arm is under a much lighter tension provided by the small friction brake by the rotating spindle 97. To provide for varying the tension between unit 125 and the arbor according to the size of wire, the amount of the kink placed in the wire is varied by changing the location of the adjustable plate 138. If this plate is moved clockwise upon its pivot 152 (see Fig. 21) the amount of the kink will be less and the tension will be less. If the plate 138 is moved counterclockwise, the kink in the wire will be increased and the amount of tension increased.

Since the wire must pass around the three pulleys 135, 150 and 160 before passing around pulley 171, the proper place to cut the wire after winding a coil is between pulley 171 and pulley 160. That portion of the wire which remains around pulleys 135, 150 and 160 remains an-

chored to the unit 125 by reason of the kink in the wire which these pulleys provide.

The mechanism for shifting the wire guide B longitudinally or parallel to the winding arbor will be described in detail later in connection with the head stock and gear box unit D. The means for supplying the paper strips P will now be described.

Paper supply device C

Referring to Figs. 22 through 27 and also 8 and 10 and 47 to 50, the table 80 supports way-blocks 190 to which are attached way-covers 191. These blocks and covers support and guide vertically slidable bars 192 to which brackets 193 are attached. The brackets 193 support a cross plate 194 which carries at each end a block 195. The block 195 and the cross plate 194 are attached to the brackets 193 by screws 196 and are located by dowels 197. Between each block 195 and the cross plate 194 there is clamped a key 198 which provides a guide for the horizontal sliding movement of a base plate 200 the position of which is adjusted by means of set screws 201 provided by each of the blocks 195. The base 200 supports vertically partitions 202 which support a shelf 203 which supports a channel shaped pan 204. The parts 200—202—203—204 are permanently joined together by welding. The pan 204 is used by the operator of the machine for holding tools and accessories. The space between adjacent partitions 202 is occupied by a stack of paper strips P. As shown in Fig. 26, the strips P rest upon an elevating platform 205 which is spring urged upwardly so as to urge the top strip of paper P against a rubber feed roller 230. The shelf 205 is attached, as shown in Fig. 23, by screws 206 to racks 207 which mesh with gears 208 carried by shaft 209 having bearings in blocks 210. Each block 210 has a stud 211 passing through a hole in a base 200 and threadedly engaging a nut 212 the tightening of which secured each block 210 to the base 200. Each block 210 provides a guide for a rack 207. The shaft 209 is encircled by a helical coil spring 213 fixed at one end 214 to a block 210 and at the other end to a cross pin 215 on the shaft 209. The spring is so biased as to urge the shaft 209 counterclockwise as viewed in Fig. 23 and the racks 207 upwardly. Thus the spring 213 operates to exert upwardly forces substantially equal upon the two end portions of the platform 205.

Each platform 205, in conjunction with the adjacent side partition 202, provides a receptacle for a stack of paper strips P. These strips are withdrawn one at a time from the stack by mechanism operated by a part of the winding head unit D. Referring to Fig. 8, just to the right of the hand wheel H is located a gear 220 which is adapted to be engaged by a gear 221 (Figs. 22 and 24) which is keyed to a shaft 222 which is supported by a plurality of sleeves 223 (Fig. 27) each of which is supported at one end by a partition plate 202. The sleeves 223 are not directly connected with the shaft 222 but are connected through a one-way clutch including a driven member 224 (Fig. 27) and driving member 225. Member 225 is integral with a hub 226 slidable on the shaft 222 and having a longitudinal spline connection therewith provided by a cross pin 225a carried by shaft 222 the ends of which extend into notches 227 provided by the hub 226. Each clutch driving member 225 is urged toward its companion clutch driven member by a spring 75

228 located between a shoulder on the driving member 225 and a washer 229 surrounding shaft 222 and bearing against an end of the adjacent sleeve 223.

5 The gear 221 is protected by a guard 240 secured to the left partition plate 202 by screws 241.

Each sleeve 223 has molded thereon a plurality of relatively soft rubber rolls 230 against 10 which the top strip of paper P is upwardly pressed by the spring urged plate 205.

By mechanism to be described the unit C can be elevated from a lower position, shown in Fig. 47, to an upper position shown in Fig. 49. In 15 the latter position the pinion 221 is brought into mesh with a gear 220. When the hand wheel H is rotated counterclockwise as viewed in Fig. 7 or clockwise as viewed in Fig. 47 and Fig. 49, the feed rollers 230 will rotate clockwise as viewed 20 in Fig. 26 to feed the top strip of paper P against a guide plate 231 which directs the top strip upwardly as shown in Fig. 26 against the guide blades or fingers F which direct the paper into the space between the wires W and the arbor 60.

The arbor 60 is manually turned counterclockwise as viewed in Fig. 26 to cause the paper to be gripped between the wires W and the arbor then the power may be applied to the arbor to keep the winding of paper thereon during the 25 power winding of a strip P of paper upon the arbor. The table 80 is lowered sufficiently to demesh pinion 221 from driving gear 220. During the power winding of paper upon the arbor, the fingers F will be located in the positions 30 shown in Figs. 2 and 51 so that the paper will be pressed smoothly around the material on the arbor as the paper is being wound. The mechanism for raising and lowering the paper slightly within the arbor and for advancing and retracting the fingers F will be described later in connection with the description of Figs. 47 through 56.

The guide plate 231 is pivotally supported, as 45 shown in Fig. 26A, by providing the plate with ears 232 notched at 233 and resting upon a cross rod 234. The plate 231 is rotatively adjustable about the rod 234 by the turning of a screw 235 accessible from the front end of the machine and having its rear end bearing against a portion of the plate 231 located below the rod 234. Plate 231 is yieldably urged against the screw 50 235 helical coil spring 237. By turning the screw 235, the front portion of the plate 231 may be adjusted relatively to the stack of paper strips 55 P and to the feed roll 230.

One very important feature of the plate 231 is that it provides means for allowing only the uppermost strip in a stack to be completely withdrawn from the stack by the feed roll 230 and to be fed upwardly against a finger F. This very 60 important feature is provided by an abrupt change in curvature of the upper end of plate 231 as indicated at 231a. As the friction wheel 230 revolves clockwise as shown by arrow 230a in Fig. 26A, it may happen that more than one sheet 65 of paper will attempt to move upwardly from the stack. This is due to the fact that one or more of the underlying strips P tend to follow the topmost strip P due to frictional engagement between the strip. When the strip next to the top engages a sort of shallow groove in the plate 231 where the curvature changes at 231a, further movement of said strip next to the top is prevented. These plates 231 are made of metal and 70 polished at least on the surface which is en-

gaged between ends of the paper strips. The reason that the topmost strip P is not stopped at the line of change of curvature (designated by 231A) is because the friction between the wheel 230 and the topmost strip is sufficient to overcome the obstruction to movement of the topmost strip by the plate 231.

The guide plate 231 is yieldably mounted for the feeding action of the rolls 230 and the pulling of the paper strip after its end is gripped between the wires and the arbor. Plate 231 is provided with ears 232 provided with oblong apertures 233 through which a pin 234 extends to provide a bearing for these ears. The oblong hole 233 provides not only for lateral movement but also some up and down movement of the plate 231. The position of the plate 231 is determined by a screw 235 accessible from the front of the machine. The screw 235 passes through a plain hole in the block 210 nearest the front of the machine and is threaded through the other block 210 and bears at its remote end against the plate 231 at a point below the rod 234. The plate 231 is yieldably urged against the end of the screw 235 by a coil spring 237.

Since each set of feed rolls 230 is connected to the shaft through a separate one-way clutch, each set of rolls is provided with an independent drive. This is necessary due to the fact that the paper strips P are not started from their respective stacks at exactly the same instant. The strip P which is started last from its stack requires a longer application of pulling force to withdraw it than the strip which is started first. Therefore the overrunning clutches are provided so that during the pulling out of the strips P by rotation of arbor 60, each feed roll 230 may be driven by the contact strip P independently of every other feed roll. It is apparent that, when a strip P has been completely withdrawn, rollers 230 which contact with that strip should be allowed to stop, although the rollers 230 cooperating with other strips continue to rotate. If the overrunning clutches were not provided by the time the last strip P has been completely pulled out from its stack the next succeeding strips might have been started out from their respective stacks. By providing the overrunning clutches the starting of the strip P other than by manual operation is eliminated.

Driving head and gear assembly D

Referring to Figs. 28 through 35 as well as Figs. 7, 8 and 14, the driving head comprises a box 250 having a right end wall 251 (Fig. 34), a partition 252 which divides the box into compartments 253 and 254. The compartment 254 is closed by a cover 255 (Fig. 33). Partition 253X separates compartment 253 from a lower compartment 253Y for housing the clutch to be described. The compartment 254 is filled with lubricating oil to approximately the level shown in Fig. 36. The level of oil in compartment 254 is indicated by a target 700 on the end of a rod 701 extending through a hole 702 in box 250 and supported by a float 703. Oil from the chamber 254 is supplied through passage 704 in partition 252 (Fig. 34) to the chamber 253 which houses the feed screws 315 and 316. These feed screws are located below the level of lubricant normally present in chambers 254 and 253 so that these feed screws are always submerged in lubricating oil. The chamber 253Y which houses the clutch is isolated from the other chambers mentioned. It is filled with oil approximately to the level of

the center of a sight glass 105 (see Figs. 8 and 34).

End wall 251 supports a ball bearing 256, and partition 252 supports a bushing 257 carrying a ball bearing 258. Bearing 256 supports a tubular main drive shaft 259 carrying a pulley 260 having a V-belt connection 261 with a pulley 262 (see Fig. 15) driven by the electric motor M. The drive shaft 259 provides bushings 263 which support one end portion of a main driven shaft 265, the other end of which is supported by bearing 258.

The driving connection between the tubular drive shaft or sleeve 259 and the shaft 265 is provided by a friction plate clutch 270 known to the trade as a Rockford Pullmore clutch. This clutch 270 comprises plates, alternate ones of which, such as plates 271, are provided with longitudinally splined connections with the cup-shaped end portion of the sleeve 259. Other alternate plates such as 272 are splinedly connected with the shaft 265. The clutch 270 provides a brake for quickly stopping the shaft 265 when it is disconnected with the drive sleeve 259. This brake is a friction disc brake similar in construction to the friction clutch drive. This brake is provided with alternate friction disc 274 keyed to the bushing 257 and alternate discs 275 keyed to the shaft 265. When the clutch 270 is moved toward the right, as viewed in Fig. 34, the plates 271 and 273 will be frictionally engaged so as to connect the drive sleeve 259 with the shaft 265. When the clutch 270 is moved toward the left, the clutch discs 271 and 273 are disengaged, and the braking discs 274 and 275 are engaged. Normally, the brake discs 274 and 275 are engaged and the clutch discs 271 and 272 are disengaged.

The clutch 270 is moved by a bifurcated block 280, the arms 281 of which are each provided with a pivoted block 282 which is received between flanges 283, provided by the clutch 270. The block 280 is fixed to a rod 285 (Figs. 29 and 30) a portion of which is tubular to provide a housing for a helical coil spring 286, confined between the end wall of the recess in rod 285, and a plate 287 attached to the end wall 251 by screws 288. The spring 286 urges the block 280 and the clutch 270 toward the left, thereby causing the friction brake discs to be urged toward a shoulder 289 provided by the shaft 265, thereby applying the brake to the shaft and maintaining the clutch disengaged.

The clutch 270 is moved toward the right by hydraulic means operating through the rod 285. Referring to Figs. 28 and 29 this hydraulic means comprises a cylinder 290 carrying piston elements 291, 292 and 293 urged toward the rod 285 by spring 294 bearing against a bushing 295 making connection with a fluid pressure pipe 296. The pipe 296 is placed in communication with a source of fluid pressure through a valve V (see Figs. 9 and 15), the actuation of which is controlled by the throttle pedal T, which is fixed to an arm 300, extending from a hub 301, journaled on a rod 302, supported by brackets 303 and 304 secured to the table 80 (Figs. 9 and 10). The arm or lever 300 is connected by a clevis 305 (Fig. 9) and a rod 306 with the valve V. The valve V is so constructed that the amount of pressure exerted by the fluid upon the rod 285 will be somewhat in proportion to the distance through which the pedal T is moved. The operator is able to control the amount of friction applied by the clutch 270 between the driving sleeve

259 and the driven shaft 265. Thus the operator may control the power applied by the motor M to the winding arbor and, therefore, the speed of the winding arbor. Another advantage of a friction clutch controlled by hydraulic means is that the application of power to the winding arbor may be gradually applied, thereby avoiding breakage of wire that might result from too sudden application of power. The Rockford Pullmore clutch is one which can be adjusted to wedge or lock in clutching condition when its control lever is moved to the limit of travel in one direction. But for the purpose of controlling the present machine, the clutch is so adjusted that it will never lock. Therefore the amount of friction afforded by the clutch to transmit torque will be in proportion to the movement of pedal T throughout the entire range of movement of pedal T. Pedal T and the bracket T₁ connecting it to the lever 300 should be made as light in weight as possible to reduce inertia to a value where the lever 300 will respond most readily to variations in foot pressure. The large pedal T and bracket T₁ shown in the drawings could be replaced by a simple stud extending laterally from the lever 300, if it is not feasible to construct parts T and T₁ of light weight metal.

The shaft 265 carries a gear 310 meshing with an idle gear 311, meshing with a gear 312. Gear 312 drives gear 313 meshing with gear 314. Gears 313 and 314 are connected respectively with screw shafts 315 and 316, which rotate in opposite directions. The screw shafts 315 and 316 are provided with screw threads of the buttress type of the same direction and value of pitch but of opposite slope. The screw 315 which rotates counter-clockwise, as viewed from the left end of the machine, is adapted to cooperate with nut section 320a on nut 320 to propel the nut 320 from left toward right. The screw shaft 316 which rotates clockwise, as viewed from the left end, is adapted to cooperate with nut section 320b to propel the nut 320 from right toward left. In order to adapt the machine for winding different sizes of wire without requiring substitution of feed screws, an adjustment of gear ratios between shaft 265 and screw shafts 315 and 316 are provided. The gear 312 may be one of a series of gears of different diameters which could be keyed upon the shaft 315. Idler 311 could also be one of a series of gears of different diameters. Idler 311 is readily adjustable on an arm 321 provided with a radial slot 322 for receiving a stud 323, upon which the idler 311 is rotatable. The stud 323 is provided with a rectangular head 324 which is received in an undercut groove 325. By loosening the nut 326 the position of the stud 323 can be varied so that the gear 311 can be brought into mesh with the gear 310, as well as into mesh with a suitable gear 312. When gears 311 and 312 are changed it may be necessary to adjust the bracket 321 rotatively. Bracket 321 is provided with a hub 327 carrying a bearing 327a journaled on a portion of the shaft 265. The bracket 321 includes an arm 328 having an arcuate slot 329 (concentric with shaft 265) for receiving a bolt 330 by which the arm 328 can be clamped to the partition wall 252 into the desired position.

A hand wheel H provides for manual rotation of shaft 265. Shaft 265 drives the gear 220 with which gear 221 meshes to operate the paper feed mechanism. The hub of gear 220 is the part D1 shown in Figs. 1 to 1E, which supports the pins 64, and 64a which makes driving connection with

the anchoring strip 70, as shown in Fig. 1A. The shaft 265 is provided with a central bore 265a for receiving the end of the arbor 60 which is driven through the crosspin 63. (Fig. 1 and Fig. 30).

5 Referring to Fig. 30 it will be observed that the tubular shaft 259 carrying an oil seal 259a frictionally engaging the shaft 265 which may remain stationary while shaft 259 is constantly rotating. If this oil seal 259a is at all effective it 10 will cause the temperature of the shaft 265 to increase to an amount which might be disagreeable to the operator whose hand makes contact with the hand wheel H. Therefore, we have provided means for thermally insulating the periphery of the hand wheel H from its hub. Hand wheel H includes a web 710, apertured to aid in the ready dissipation of heat, which is attached by screws 711 to spaced arms 712 of an apertured plate 713 integral with a hub 714 keyed to shaft 20 265 as shown in Fig. 30. The web 710 is not directly in metal contact with the arm 712 but is thermally insulated therefrom by fiber blocks 715. Heat developed in the shaft 265 is dissipated to a large extent by the apertured web 25 713. Any small amount of heat not blocked by the fiber blocks 715 is dissipated by the apertured web 710. In addition to the foregoing, the pulley 260, which is constantly rotating, drives a fan 716 which blows cool air through the perforated webs 713 and 710. The fan 716 and the pulley 260 are enclosed by perforated guard 717. In this way the hand of the operator which must 30 come into contact with the hand wheel H is protected from injury due to heat developed 35 by the frictional engagement with the shaft 265 of the oil seal ring 259a and from injury due to contact with the fan 716 and pulley 260 and belt 261.

The nut 320, comprising threaded segments 40 320a and 320b, engageable with feed screws 315 and 316 respectively, is provided at one end of a bifurcated block 340 (Fig. 43) provided with bearing bushings 341 (Figs. 32 and 33) by which the block is journaled on a rod 342. Rod 342 is connected by cross pin 343 with a tube 344 which is supported by bearing 345 in the partition 45 252. The tube 344 is provided with a longitudinal opening 346 into which a nut member 347 may extend into engagement with a threaded portion 348 of rod 342, provided the tube 344 is located with the opening 346 in the uppermost position, as shown in Figs. 28, 32, and 33A. The nut 347 is attached by screws 349 to a lever 50 350 fixed to a shaft 351, journaled in partition wall 252 and end wall 251 of housing 250.

The purpose of the engagement of the nut 347 with the screw threads 348 of rod 342 is to prevent accidental shifting of the wire guide unit B with which the rod 342 is connected. It is apparent that there should be no accidental shifting of the guide unit B while the member 340, which provides nut sections 320a and 320b, is out of engagement with both of the feed screws 315 and 316 as shown in Fig. 43. Under these 60 circumstances the nut 347 engages the screw 348 as shown in Fig. 33A. The tube 344 is rotated concurrently with the nut block 340 by mechanism to be described later. By the time that the nut block 340 has been rotated sufficiently to bring either of its nut sections 320a or 320b into full engagement with feed screws 315 and 316, respectively, the tube 344 will have been moved sufficiently to cause the nut 347 to be cammed out of engagement with the screw 75 348 of rod 342 thereby releasing rod 342 to per-

mit the transversing movement of the wire guide unit B. It is, therefore, apparent that when the nut block member 340 is in neutral position as shown in Fig. 43, the wire guide unit B is locked against longitudinal movement.

Since it is necessary at the beginning of coil winding operation to restore the wire guide unit B to the start position while the nut block 340 is in neutral position, we have provided means independent of the tube 344 for elevating the nut 347 from the screw 348 or rod 342. This is accomplished by a mechanism operated by a hand-grip lever 361 associated with control lever 360 which is also designated as the wire guide control lever GC in Fig. 7, as well as Fig. 43. This mechanism comprises shaft 351 which carries an arm 352 which is connected by link 354 (Fig. 43) with a lever 355 pivoted on a bracket 356 secured to the underside of table 80. Link 354 extends through the bottom wall lubricating oil containing compartment 253Y of the box 250. To prevent oil flowing out an opening provided for this link in the bottom wall of the box 250, the link 354 is surrounded by a tube 411 fixed to the bottom wall of the housing 250 and extending to a level which is above the level of oil placed within the compartment 253Y. Lever 355 may be pushed downward by plunger 358 slideable in a pin 359 which pivotally secures a bifurcated lever 360 through the table 80. The lever 360 is provided with a pivotally mounted hand-grip lever 361 having an arm 362 which is forked around a part of the plunger 358 and which bears against a shoulder 358a thereof. The movement of the hand-grip 361 toward the lever 360 causes the plunger 358 to move downwardly, thereby downwardly moving the lever 355 and the link 354 which causes the arm 352 to move downwardly and the lever 360 to move upwardly, thereby moving the nut 347 from the tube 344, and disengaging the nut 347 from the threaded portion 348 of rod 342. This permits restoring the wire guide B to start position by means of the control knob marked GR in Fig. 7 to be described later.

The lever 360 is mounted to swing in a horizontal plane, as viewed in Fig. 43, and to effect the movement of a link 365 horizontally. Link 365 is attached to a lever 366 keyed to a shaft 367 journaled in a bracket 368 and carrying a lever 369 the upper end of which supports a threaded stud 370 carrying pairs of nuts 371 and 372 which may be threaded along the stud 370 for purposes of adjustment. Between the pair of nuts 371 is clamped a collar 373 and between the pair of nuts 372 is clamped a collar 374. Collar 373 is connected by link 375 with a block 377, pivotally connected by pin 379 with an arm 381, secured by pin 383 to shaft 342, to which the tube 344 is pinned. The collar 374 is connected by a bent link 376 with block 378 pivotally attached by a pin 380 to an arm 382 which is an integral part of the nut block 340 carrying nut member 320 providing the nut segments 320a and 320b. The nut member 320 is held in either of its extreme positions in engagement with screw 315 or with screw 316 by yielding means comprising a spring 390 attached at its lower end to a lever 391 pivoted upon a rod 392 carried by the bracket 368 and having a short forked arm 393 engaging a pin 394 carried by the arm 369. As shown in Fig. 43, the spring 390, the arms 391 and 393, and the arms 366 and 369 are all in alignment. These are the positions which they occupy when the hand

lever 360 is in the center or neutral position N. When the lever 360 moves to the position R, the nut member 320 will be moved into engagement with the screw shaft 315, which is the shaft which causes the nut 320 to be fed toward the right (Fig. 34) and likewise the wire guide unit B toward the right (Figs. 8 and 10). In a similar fashion the nut 320 is caused to engage the shaft 316 by movement of the hand lever 360 into the position L shown in Fig. 45. In which position the machine is conditioned for movement of the nut 320 and the unit B from right toward left. In either of these positions of the nut it is maintained yieldable by the spring 390. When the hand lever 360 is moved to the "R" position, levers 366 and 369 move clockwise and lever 391 moves counterclockwise to the position 391R, thereby shifting the center line of action of the spring 390 toward the right of the axis of shaft 367, thereby urging the threaded member 370 clockwise to position 370R, the link 376 toward the right and the nut 320 toward the left or clockwise into engagement with the screw shaft 315. Conversely, when the lever 360 is moved to the L position the lever 391 is moved into the position 391L, thereby moving the center line of action of the spring 390 to the left of the axis of shaft 367, thereby urging the threaded rod 370 toward the left into the position 370L, thereby urging the link 376 toward the left and the nut 320 toward the right. At the same time the arm 381 is urged clockwise or counterclockwise by the spring 390 as it urges the nut 320 clockwise or counterclockwise. This effects the turning of tube 344 attached to rod 342 to cam the nut 349 away from screw 348 of rod 342 to release the wire guides B for movement along the arbor 60. When the lever 360 is in neutral (N) position the nut 349 engages screw 348 of rod 342 to prevent accidental shifting of guides B as shown in Fig. 33A.

Upon the completion of the winding of a coil the nut block 340 is moved to neutral position, in which position it remains so long as the lever 360 remains in the neutral or N position. Lever 360 is retained in this position by a detent 360a urged into a detent recess of lever 360 by a spring 360b. While the lever 360 remains in the neutral position and the nut block remains out of engagement with feed screws 315 and 316, the operator will wish to move the wire guide unit B to start position. In order to be able to do this the operator must first retract the nut 347 from the screw 348 of rod 342. This is accomplished by squeezing the lever 361 against the lever 360 while the latter remains in neutral position in order to cause lever 355 and 352 to move downwardly and lever 350 carrying nut 347 to move upwardly as previously explained.

The movements of the nut 320 imparted to it by both of the screw shafts 315 or 316 are transmitted to the tube 121 of the guide unit B by the rod 342 to the right hand end of which is clamped a sleeve 400 (see Fig. 32A), which is keyed by key 400a to the rod 342. Nut 400b cooperates with threaded end 401 of rod 342 to secure the sleeve 400 to the rod 342. The sleeve 400 is provided with a screw thread 402 which cooperates with a screw pin 403 threaded through a tube 405 slideable through a bearing 406 provided by the end wall 251, and connected by a cross pin 407 with the tube 121. While the nut block 340 is moved out of engagement from one feed screw and into engagement with the other feed screw (feed screw 315 and 316), the rod 342 rotates. During a por-

tion of the shifting movement of the nut block 340, the nut 347 remains in engagement with screw 348 of rod 342 and thus limits any movement of rod 342 to a very small amount. The pitch of screw 402 being much greater than the pitch of screw 348 it follows that, while the rod 342 rotates, a substantial longitudinal movement of the sleeve, 405, the tube 127 and the wire guide unit B takes place. There is sufficient shifting of unit B to prevent the first turn of a new layer being directly superposed upon the last turn of the preceding layer of wire wound upon the arbor.

In the normal use of the machine the operator stops the winding operation after a predetermined number of turns have been wound on a layer by the release of a throttle pedal T. Should the operator fail to do so the machine will not be wrecked because the feed nut will be automatically cammed out of engagement with the feed screw. For this purpose the feed screw is provided with a conical camming surface 315A, which will be engaged by the nut 328 at the end of its travel to the right along the screw 315. Similarly, the screw shaft 316 is provided with a conical cam 316A also for the purpose of throwing out the nut 328 automatically at the end of its travel toward the left of the screw 316. Therefore the winding might continue, the wire guide unit B will not be forced beyond the allowed limits of its travel and be caused to bear against some stationary part which would react destructively upon the fine screw threads of the threaded shafts 315 and 316.

Referring to Figs. 10 and 14, the restoration of the wire guide unit B toward the left, which is the starting point for the beginning of the winding of a coil is effected by a lever 420 pivoted at 421 upon a bracket 422 pivoted at 423 upon a bracket 424 fixed to a pedestal 425 supported by the table 80 and providing a bearing 426 for the sliding movement of the tube 127. The lever 420 is urged in a clockwise direction (Fig. 14) by a spring 427 attached to one end of the bracket 424, and at the other end to the lever 420. Clockwise rotation of the lever 420 is limited by a stop screw 428. Movement of the lever 420 by its knob 420a from the right towards the bracket, as viewed in Fig. 10, is limited due to the fact that the end of the lever 420 remote from the operator moves from left toward right and engages a stop screw 430 carried by a bracket 431 fixed to the bracket 424. The lever 420 carries a pin 433 adapted to be received by a notch 434 located between two lugs 435 on a clamp bracket 436 adjustably secured to the tube 127. To restore the wire guide unit B to normal start position at the beginning of the winding of a set of primary coils, the operator places his left hand around the levers 360 and 361 and squeezes the latter toward the former in order to retract nut 347 from screw 348. While thus gripping the lever 361 against lever 360 the operator uses the right hand to manipulate the lever 420 so that the pin 433 will be received in the notch 434 between the lugs 435, and the lever 420 is moved by the operator toward the left as far as it will go as limited by the lever striking the stop screw 430. Then the operator releases lever 420 whereupon the spring 427 restores the lever to a position out of engagement with the wire guide unit B. The operator then releases the hand grip lever 361 to permit spring 357 acting upwardly through link 354 to cause the levers 352 and 358 to rotate clockwise as viewed in Fig. 43 to restore the nut 347

into engagement with screw 348 as shown in Fig. 33A. Spring 350A (Fig. 28) also effects restoration of nut 347 into locking position. The unit B is then in proper position for starting to wind a set of coils.

Tail stock unit E

The tail stock for supporting the right-hand end of the winding arbor is shown in Figs. 38-42. It comprises a frame 460 to which screws 461 attach keys 462 which slide in ways provided by T-slots 463 provided by the table 80. The T-slots 463 receive nuts 464 threaded on the ends of screws 465. When the screws 465 are loosened from their nuts 464 the tail stock may be moved along the table 80 in a direction parallel to the arbor so that the distance between the tail stock unit E and the head stock unit C may be varied to accommodate arbors of different lengths.

The tail stock frame 460 supports and guides a horizontally movable sleeve 466 providing a rack 467 meshing with a gear 468 pinned to a shaft 469 journaled in the frame 460 and keyed to an operating handle 470. Rotation of the sleeve 466 is prevented by screw pin 471 threaded through the frame 460 and entering a longitudinal groove 472 provided by the sleeve 466. The sleeve 466 supports ball bearings 473 and 474 which support a tail stock spindle 475 the head of which provides the member E1 (Fig. 1) which carries the pins 65 and 65a. The arbor 60 is driven by the shaft 265 through the cross pin 63 (Figs. 1 and 30) and the arbor 60 drives the spindle 475 through a connection which includes a rod 480 having, at its left end, a blade 481 adapted to be received by a cross notch in the end of the arbor which is received in the cylindrical recess 476 provided by the spindle 475. The rod 480 is connected with spindle 475 by a pin 482 fixed to the rod 480 and having its ends received by longitudinal slots 483 provided by the spindle 475. A spring 485 received by the cylindrical bore 486 of the spindle 475 urges the rod 480 to the left until the pin 482 engages the left-hand ends of the slots 483. When the arbor 60 is mounted upon the spindle 475 the rod 480 will be pushed slightly toward the right from the position shown in Fig. 39. In this manner the spindle 475 supports the arbor 60 and is drivingly connected therewith through the pin 480 which is yieldingly urged into engagement with the arbor.

To clamp the tail stock spindle against the right end of the arbor 60 the lever 470 is moved from right toward left (Fig. 38). The lever 470 is held in this position by a friction clamp QC known to tool designers as a "Q. C." clamp which is purchased on the market. This clamp is one which binds frictionally when movement of the tail stock spindle toward the left is resisted by the further compression of the spring 485 which urges the rod 480 against the arbor 60. To remove the arbor from the tail stock, the lever is moved toward the right (Fig. 38) to cause the clamp QC to release and to effect retraction of the rod 480 from arbor 60 by further movement of lever 470.

Indicator unit or revolution counter I

The turn indicator or revolution counter is illustrated best in Figs. 35, 36 and 37. The shaft 265 drives a worm 500 meshing with a gear 501 keyed to a shaft 502 journaled in a bearing 503 supported by the bottom wall of housing 250 and in a bearing 504 journaled in a housing 505 se-

cured to the top wall of housing 250. Housing 505 encloses a worm 506 driven by shaft 502 and meshing with a worm wheel 507 pinned to shaft 508. Shaft 508 is journaled in a bearing 509 supported by housing 505 and in a bearing 510 supported by a housing cover 511. Shaft 508 drives a washer 512 retained on the shaft by nut 513. Toward this washer 512, a spring 514 urges a washer 514a and an assembly of pointer 515, cable reel 516 and timing disc 517 which are fastened together and are loosely mounted on the shaft 508. The assembly of pointer, cable reel and timing disc is frictionally driven by shaft 508. The pointer 515 cooperates with a plate 520 to indicate the revolutions of the arbor and hence the number of turns of wire being wound on the arbor. The timing disc 517 is provided with arcuate slots 521 each for receiving the threaded shank of screw 522 which cooperates with a nut 523 to secure the screw in the desired position of adjustment in the slot 521. Each of the screws 522 cooperate with a lever 524 pivoted at 524a on a bracket 525 attached to the cover 250A of the gear housing 250. The lever 524 is urged downwardly by a spring 526 attached at one end to lever 524 and at the other to a stud 527 mounted on a post 528 extending from cover 250A. Lever 524 carries a screw 529 threaded through the lever and locked in position by nut 530. The lower end of screw 529 engages plunger 531 of switch 532 mounted on bracket 525. When the plunger 531 is in the position shown in Fig. 35 the electric switch 532 is closed to establish a circuit between a current source and an indicator lamp 533 supported by the unit B shown in Fig. 8. The lighting of the indicator lamp 533 signals the operator of the machine that a sufficient number of turns of wire have been wound on the arbor to complete a layer of winding. Therefore the operator stops the machine and applies a layer of paper and reverses the feed of the machine and starts winding another layer. As shown in Fig. 35 the screws 522 are so located on the timing disc 517 that the indicator lamp 533 will be caused to burn at the end of winding the 60th turn, after winding the 115th turn, after winding the 165th turn and after winding the 210th turn. By means to be described the pointer 515 is set to zero before starting to wind a new coil. Fig. 35 shows that the pointer 515 has moved to 60 and that one of the screws 522 has lifted the lever 524 to a position in which the stop screw 529 carried thereby will clear the switch plunger 531 thereby permitting the closing of the switch 532. The signal lamp 533 therefore is lighted to indicate to the operator that 60 turns of wire have been wound on the arbor. Sixty turns being the prescribed number of turns for the first layer, the operator stops the machine feeds paper strips between the first layer and the wire from the supply reel then the operator turns the arbor manually to start the paper upon the arbor first layer of wire and reverses the direction of feed of the wire guide assembly and then starts the machine. The pointer 515 then moves up to the 115 mark on the dial 520 and the indicator lamp 533 burns again to indicate that the second layer of wire contains the required number of turns, which in the example given would be fifty-five turns (115 minus 60). In a similar manner indications are given for the stopping of the machine at the end of the winding of the 3d and 4th layers of turns. The disclosed setting of the screws 522 will give visible indication when fifty turns have been wound on the 3d layer and

forty-five on the 4th layer. At the end of the winding operation of four layers the pointer 515 is returned to zero position in a counter-clockwise direction against a stop pin 534. This manually operable pointer restoring means is coordinated with the tail stock unit E.

The movement of lever 470 toward the right as viewed in Fig. 38 to release the tail stock spindle from the arbor effects the operation of the means for resetting the indicator unit I to the zero position. Referring to Figs. 41 and 42 the shaft 469 supports a disc 540 fixed to the shaft by pin 541 and providing a recess 542 defined by an annular segment 543 ending in abutment surfaces 544 and 545. The recess 542 receives the hub 546 of a lever 547. Lever 547 is confined in the recess 542 by a disc 548 secured to shaft 469 by a pin 549. In this way a lost motion connection is provided between the handle 470 and the lever 547. Lever 547 slidably supports a rod 550 having an eye 551 to which is attached wire 552 which extends over to the indicator unit I and there passes over the spool 516 as shown in Fig. 37. The wire 552 passes around pulleys and through guide tubes shown in Fig. 35 such as pulleys 553 and 554 and guide tube 555. When the handle 470 which is also marked IR in Fig. 7, is moved toward the right as viewed in Figs. 7 and 38, the shaft 469 is moved clockwise as viewed in Figs. 38 and 39 and counterclockwise as viewed in Fig. 42. This causes the abutment surface 545 of disc 540 to engage the lever 547 thereby causing it to move counterclockwise and to pull the wire 552 toward the left which causes the wire 552 to be unwrapped from the spool 516 shown in Fig. 37 thereby causing the pointer 515 to move counterclockwise back to the stop pin 534. When the lever 470 is moved in the opposite direction to clamp the tail stock against the arbor the shaft 469 rotates counterclockwise thereby moving the abutment surface 545 away from the lever 547. There is sufficient clearance between the abutment surfaces 544 and 545 so that the clamping movement of the lever 470 may take place while the lever 547 remains in the reset position. During winding of a coil the pointer 515 is free to move and the spool 516 moves with it to wind up the wire 552 thereon which causes the lever 547 to move clockwise as viewed in Fig. 42. At the end of the winding operation the lever 547 will be substantially in engagement with the stop 545 so that the return of the handle 470 into arbor disengaging position will effect the return of the pointer 515 to zero position.

The wire 552 is either pulled by the lever 547 or pulled by the spool 516; therefore it is always in tension while transmitting motion. Therefore the wire 552 is made of braided fine wire. It is maintained in tension by spring 556 which, as shown in Fig. 42, surrounds the rod 550 and is maintained between washers 557 and 558, the latter being retained by a nut 559 threaded on the rod 550.

Knife control pedal KC

The upper or normal position of the knife control pedal KC is shown in Fig. 49 and the lower or operating position in Fig. 47. Pedal KC is adjustably secured to a pedal lever 560 pivotally supported on rod 561 which is supported by two brackets 562 and 563 supported on the floor. Spring 560a restores pedal KC to upper position. Brackets 562 and 563 are tied together by rod

564. Rods 561 and 564 support a stop bracket 565 shown in Figs. 47 and 49. To the lever 560 there is adjustably secured a plate 566 which is connected by link 567 with a lever 568 loosely journaled on the shaft 302. Lever 568 is provided with a notch 570 receiving a pin 571 carried by an arm 572 keyed to a shaft 573. To the shaft 573 are keyed a plurality of arms 574 provided with screw actuated clamping ends 575 which can be clamped around a rod 576 thus tying together all of the arms 574. Preferably there are three of these arms 574, one near each end of the arbor 60 and one intermediate. The rod 576 supports a plurality of arms 577 which are supported also by a rod 578 having an eccentric 579 at each end. Holes provided in the bracket 183 (Fig. 50) receive the eccentric 579. By turning the rod 578 about the axes of the eccentrics 579 the height of the rod 578 can be adjusted. The eccentrics 579 are secured in the desired position of adjustment by the tightening of a screw 580 which draws up nut 581 and a bushing 582 against the sides of the eccentric 579. In order to adjust the brackets 183 along the table 80 in a direction parallel to the arbor 60 the table is provided with a T-slot 583 which receives a slide 584 with which the bracket 183 is provided. The brackets 183 are secured in the desired position of horizontal adjustment by screws 585 engaging nuts 586 received by the T-slots 583.

Each arm 577 carries a knife K. The number of arms 577 and knives K will be equal to the number of divisions to be made between the coils wound on the arbor. For example if 10 coils are wound 9 divisions will be required to separate the coil units. It is apparent from Figs. 47 and 49 that downward movement of the pedal KC to the position shown in Fig. 47 will effect movement of the knives K from nonoperating position (Fig. 49) to operation position (Fig. 47). Release of pedal KC permits spring 560a to restore pedal KC to upper position and the return of knives K to nonoperating position. As the knives thus move they are guided into the cutting position by movement of their arms 577 along the rod 578 which is adjusted in the manner referred to in order to locate the knives K in the proper position for severing the coil units on the arbor.

The upper end of spring 560a is attached to a clevis-rod 560b pivotally connected with a lever 560c clamped around shaft 573. Spring 560a continually urges shaft 573 and arm 572 clockwise in order to take up all lost motion between pin 570 and the lever 568.

Referring to Fig. 49 the end of each knife supporting arm 577 is bifurcated, thus defining a notch, one end of which is designated by the bottom line 577a. Within this notch and surrounding the rod 576 there is located a split washer 577b having a width slightly less than the width of the notch. This washer can be clamped around the rod 576 by means of a clamping screw in order to maintain the arm 577 in the desired position of adjustment along the rod 576. This adjustment for each of the arms 577 provides for the proper location and spacing of the knives K.

Paper control pedal PC

Referring again to Figs. 47 and 49, the paper control pedal PC is adjustably secured to a pedal lever 588 which is also pivotally supported on rod 561 and operates between set screws 589 and

590 supported respectively by lugs 591 and 592 carried by the plate 565. (It will be understood that the lever KC operates between screws supported by similar lugs on the reverse side of the plate 565.) Blocks 593 and 594 are adjustably secured to the lever 588 on opposite sides thereof as shown in Fig. 9. Block 593 is on the near side of lever 588 as viewed in Figs. 47 and 49 and block 594 is on the reverse side. Block 593 is connected with a link 595 which passes through a block 595a and receives nuts 595b limiting downward movement of the link 595 relative to said block. Block 595a is pivotally attached to a lever 596. Lever 596 which is keyed to the shaft 302 which supports and drives two beams 597 which are adjacent brackets 303 and 304 respectively as shown in Figs. 9 and 10. Each beam 597 is connected by an adjustable link 598 with one of the table brackets 193. Each beam 597 is connected by a rod 599 with a counterweight 600. The weights 600 tend to counterbalance the table unit C and its operating mechanism but are slightly overbalanced by unit C so that unit C will gravitate, when released, to lowest position shown in Fig. 47. Spring 588a attached at its lower end to lever 588 and at its upper end to table 80 normally maintains pedal PC in upper position (Fig. 47). When the lever PC is pushed downwardly, the paper supply unit C is moved upwardly from the position shown in Fig. 47 to that shown in Fig. 49 in which position its operating gear 221 meshes with the driving gear 220 carried by the arbor shaft 265 shown in Fig. 34.

The downward movement of the pedal PC 35 moves the blades or fingers F from the most retracted position shown in Fig. 47 to the most advanced position shown in Fig. 49 through a link 601 connected with block 594 and with a lever arm 602 keyed to a shaft 603 supported by 40 the table 80. Shaft 603 is keyed to levers 604 which support a rod 605. Rod 605 supports a plurality of bars 606 each supporting a blade or finger F. Each bar 606 is supported by a roller 607 pivotally supported by a post 608 adjustably 45 supported for vertical adjustment by a bracket 609 (Fig. 48). The brackets 609 are supported for horizontal adjustment along the table 80 in the same manner as provided for in the adjustment of brackets 183. Each post 608 is adjusted 50 vertically by the turn of a screw 610 and is secured in the desired position of adjustment by a screw 611 passing through a slot 612 in the post 608 and threaded into the bracket 609.

The number of bars 606, fingers F and posts 55 608 equal the number of separate coil units being wound upon the arbor. That part of each finger supporting bar 606 which surrounds the rod 605 is bifurcated to provide a notch, the end of which is indicated by the broken line 606a in 60 Fig. 49. Within this notch and surrounding the rod 605 there is located a split clamping washer 606b having a width slightly less than the width of the notch. The split washer 606b can be clamped by screws around the rod in the desired 65 position of adjustment in order that the bar 606 and its finger F may be located in the proper position with respect to the work. Similar lateral adjustment of the bracket 609 and posts 608 for supporting each bar 606 will be made. Since the 70 knife supporting arms 577 and the finger supporting posts 608 can be adjusted laterally in directions parallel to the arbor 60, the knives K and the fingers F may be properly located for cooperation with coil sections varying in number and length, which are wound upon the arbor.

In order to start the withdrawal of paper strips P from the paper supply unit C, and to move the leading ends of these strips in between the wires W and the material being wound on the arbor, the operator first moves the pedal PC from the position shown in Fig. 47 to that shown in Fig. 49, thereby causing the link 595 and the lever 596 to move downwardly, thereby causing the beam 597 to rotate clockwise to move the link 598 and the unit C upwardly into the position shown in Fig. 49, in which position the pinion 221 of the unit C meshes with the gear 220. Then the operator turns the handwheel H in clockwise direction, as viewed in Fig. 49, in order to cause the paper strips to be withdrawn and to be fed against the wires W, said strips being directed against the wires by the fingers F, as has been previously described with reference to Fig. 47. By pressing the pedal PC the operator causes power to be applied to the arbor 60 to cause the paper strips to be wound upon the arbor while winding a few turns of wire thereon.

Prior to the power winding of the paper strips upon the arbor, the operator diminishes foot pressure upon the pedal PC to permit it to move from the position shown in Fig. 49, to that shown in Fig. 51. In this position the pinion 221 is demeshed from the gear 220 and the fingers F are caused to resiliently bear against the work on the arbor causing the finger supporting bars 606 to move downwardly by reason of the fact that the notches 613 provided by the bars 606, each receive a roller 607. Since the fingers F are permitted to bear resiliently against the paper which has been started on the arbor, the paper strips are caused to be ironed out by the fingers so that the strips will be wound around the arbor without wrinkles or bulges.

At the time that the fingers F are resiliently located upon the material being wound on the arbor 607, as shown in Fig. 51, one of the beams 597, which actuates the paper supply unit C is caught by latch pin 617 which obstructs further counterclockwise movement of beam 597 and further downward movement of unit C. (This latch pin 617 and its operating mechanism will be described more fully in connection with Figs. 54, 55 and 56.) Therefore it is not at all difficult for the operator to hold the pedal PC in the position shown in Fig. 51, for he is no longer required to transmit any supporting pressure to the paper supply unit C. All he is required to do is to overcome the pull of the spring 588a sufficiently to retain the bars 606 in the position shown in Fig. 51, at the time the bars 606 drop over the rollers 607, as shown in Fig. 51. The dropping of the bars 606 over the rollers 607 assists the operator in holding the pedal PC against the action of spring 588a.

After the winding of a few turns of wire upon the arbor around the strip of paper wound thereon, it is necessary to retract the fingers F in order to complete the winding of the layer of wire turns upon the arbor. In order that the fingers F may be retracted, the operator releases the pedal PC entirely to cause it to move from the position shown in Fig. 51 to that shown in Fig. 53, thereby causing links 601 and 595 to move upwardly. Upward movement of link 595 may take place without moving the beam 597, since link 595 has only a one-way connection with the block 595a. Upward movement of link 601 effects clockwise movement of levers 602-604 and movement to the right of bars 606 and fingers F. Before the bars 606 can move to the right,

from the position shown in Fig. 51, to that shown in Fig. 53, these bars must all be elevated with respect to these rollers 607. The lifting of the bars 606 places extra work upon the spring 588a. 5 If spring 588a were made strong enough to do this extra work, it would be unusually stiff and would require the application of unusually heavy pressure of the pedal PC in order to switch the spring when moving the pedal upwardly in the 10 position shown in Fig. 49. Therefore, there is provided a spring booster which comes into action when it is necessary to lift the finger bars 606.

The spring booster will now be described with 15 reference to Figs. 51 and 52. A bracket 730 mounted on table 80 supports a cylinder 731 enclosing a plunger 732 carrying a roller 733 urged by spring 734 against a cam 735 mounted on shaft 603. The cam 735 is provided with two 20 concentric lands 736 and 737 joined by a rise 738. The cam 735 is so located with respect to the shaft 603 that, when the finger bar notches 613 receive the rollers 607, as shown in Fig. 51, the roller 733 bears against the rise 738 near 25 where it joins the land 737. Therefore, when the operator releases the pedal PC, to permit it to move from the position shown in Fig. 51 to that shown in Fig. 53, the spring 734 is lifted to exert a pressure transmitted through the 30 plunger 732 and roller 733 to cause the cam 735 to rotate clockwise and thus assist the spring 588a in overcoming resistance to upward movement of finger bars 606 while they move toward the right toward the position shown in Fig. 53. 35 The compression of spring 734 is adjusted by a screw 740 threaded into the cylinder cup 741 and retained by a lock nut 742. Obviously extra additional effort is required to compress spring 734. But this is no objection because the operator is 40 not required to continue the additional effort required to compress spring 734 after the cam 735 has been moved so that its land 737 is engaged by the roller 733. In other words, when the pedal PC is in the position shown in Fig. 49, the only 45 pressure required to be exerted by the operator is that which is required to stretch the spring 588a plus the differential between the weight of the paper supply unit C and the counterbalances 606.

50 The latch 617 and its actuating mechanism will now be described with reference to Figs. 54-55 and 56. The bracket 304, which is secured to the underside of the right hand end of the table 80, is provided with a counterbored recess 619, which carries a plunger 617 having a flange 618 of a smaller diameter than the counterbore 619, and carrying, near its left end, a threaded collar or nut 620, threadedly engaging the plunger 617, and held in adjustment by a set screw 621. Plunger 617 is surrounded by a coil spring 622 bearing at one end against the flange 618 and bearing at its other end against a retainer plate 623 which is secured in a recess 55 in the bracket 304 by screws 624. Collar 620 cooperates with a rod 625 which is secured by welding to a plate or pad 626. The pad has a lug 627 which is hinged by a pin 629 to a pair of lugs 628 integral with bracket 304. As stated before, 60 the bracket 304 supports the shaft 302 carrying the beam 597 having near its center a stop pad 630 which also has a camming surface 630a shown in Fig. 56. This camming surface will allow unhampered upward movement of the table C or clockwise movement of the beam 597 as

viewed in Fig. 49. On downward movement of table C or counterclockwise movement of beam 597 this stop pad 630 strikes the projecting end 631 of plunger 617 causing the beam 597 and table C to stop in the desired position, as shown in 51 and 52. To release beam and allow table C to return to the position shown in Fig. 47, the operator pushes with the side of his knee on pad 625 which rotates counterclockwise on hinge pin 629 causing rod 625 to strike collar 620, thereby causing plunger 617 to move to the left thereby releasing beam 597 and permitting the unit C to descend by gravity. The latch pin 617 is released only at the completion of the winding of coils upon the arbor. Between the winding of successive layers of wire and paper strips, the unit C is not permitted to descend below the position shown in Fig. 51. The only required elevation of the unit C is from the position shown in Fig. 51, to that shown in Fig. 49 until all of the paper strips have been applied to the arbor. After winding on the last coil and securing its end lead to the coil in the manner shown in Fig. 6B, then the operator pushes on the knee pad 629 to effect the retraction of the latch 617 to allow the unit C to gravitate to the position shown in Fig. 47. This is done in order to provide access to the arbor 60 for its removal and replacement of another supporting secondary coil on which primary coils are to be wound.

Operating instructions

Place the arbor 60 containing the secondary winding in position between the head stock D1 and the tail stock E1. First, connect the notch 62 in the left-hand end of the arbor 60 with the pin 63 in head stock D1, and align tail stock element 481 (Fig. 39) with the slot in the right-hand end of the arbor 60. Then move lever 470 counterclockwise, Fig. 7, in order to lock the tail stock element E1 in arbor supporting position. This operation will cause a lost motion connection to be placed between member 540 (Fig. 42) and member 547, so that the pointer 515 (Fig. 37) will be free to move from zero position. (The pointer 515 was returned to zero position by clockwise movement of lever 570, Fig. 7, in order to retract the tail stock member so that the arbor with its completed windings could be removed.)

Turn the arbor into a position such that the hidden secondary leads 61a (Fig. 6b) are located at the rear of a vertical plane intersecting the axis of the arbor. The pins 64 and 64a of element D1 and the pins 65 and 65a of element E1 will be located approximately as shown in Fig. 1. Place the anchoring or drive strip 70 in position as shown in Fig. 1A upon the pins 64 and 65. In this position, the drive strip 70 remains flat.

Reset the wire guide unit B in normal or start position by using the left hand to grip the lever 361 toward lever 360 (Fig. 44) in order to lift the locking nut 341 from the screw threaded end 348 (Fig. 33A) of rod 342. This unlocks the wire guide unit D to permit it to be moved to start position although the nut segments 320a and 320b (Fig. 43) engage neither of the feed screws 315 or 316. While gripping the lever 361, the operator places his right hand on the guide return lever GR which is first pushed down to cause its pin 433 (Fig. 10) to enter a notch 434 between lugs 435 carried by the wire guide supporting tube 127. While the lever GR is held in this position, move the handle of the lever toward the left until the rear part of lever GR

strikes a stop screw 430 which is positioned so as to locate the wire guide unit B in the correct starting position. Then release lever GR and hand grip lever 361.

- 5 Pull the wires W through the wire tension devices provided by the brackets 125. Thread the wires between the flanges 174, 175 (Fig. 18) and over the pulleys 171. Pass each wire through a hole 12 of the anchoring strip 70 and then under the anchoring strip and bend the end of each wire through the notch 11 as indicated at W3 in Fig. 1B.
- 10 Place three spring clips 76 over the strip 70 in order to cause the strip to be bent around the secondary windings 61. Then move guide control lever GC toward the left (Fig. 7) which is the same as moving lever 360 (Fig. 45) to the R position. This causes nut 320a to engage feed screw 315 for the purpose of causing the wire guide B to traverse from left toward the right of the arbor 60. Then press the pedal T for an instant to cause a few turns of wire to be wound upon the drive strip 70 while the clips 76 remain thereon. Since the few turns of wire will hold the strip 70 in cylindrical formation, the clips 76 are then removed. Then the operator presses the pedal T again to complete the winding of the first layer of wire turns. The completion of this layer is indicated by the burning of the lamp 533 (Fig. 8) which, according to the setting of the indicator I (Fig. 35), indicates that 60 turns of wire have been wound upon the first layer.
- 15 Place guide control lever GC toward the left (Fig. 7) which is the same as moving the lever 360 (Fig. 45) to the L position thereby causing nut segment 320b to engage feed screw 316 in order that the wire guide unit B will traverse from right to the left (Fig. 7).
- 20 Depress the pedal PC to its lower limit thereby causing paper supply unit C to be elevated to the position shown in Fig. 49 and the fingers F to be located slightly in front of and spaced above the arbor. This causes the pinion 221 of the paper supply unit C to mesh with the arbor gear 220 so that the paper supply unit is operatively connected with the machine. By turning the hand wheel H or by momentarily depressing the pedal T, the gear 220 is caused to rotate clockwise as viewed in Fig. 49 and the pinion 221

- 75

counterclockwise in order to feed strips of paper to the arbor as indicated in Fig. 1E. The fingers F direct the paper strips P in between the first layer of the wires on the arbor and the wires W leading thereto from the wire supply spools. Then release the pedal PC slightly to allow it to move into the position shown in Fig. 51 in which position the fingers F will bear upon the paper strips P while they are being wound upon the arbor 60. The pinion 221 is then demeshed from the gear 220 and the unit C is held in the position shown in Fig. 51 against gravity due to the fact that the latch 617 has automatically locked the beam 597 which supports the table C.

While holding pedal PC in the position shown in Fig. 51, press pedal T in order to cause the arbor to wind the paper strips P completely around the arbor. Following this operation, release the pedal PC to permit it to return to the position shown in Fig. 53 in which position the fingers F are entirely retracted from the arbor while the paper supply unit C remains in the position shown in Fig. 53. Then press pedals T again to cause the second layer of wire turns to be completely wound upon the arbor. The pedal T is pressed until the lamp 533 burns again to

indicate that the total number of wound coils is 115, the second layer having, therefore, 55 coils.

Release the pedal T to bring the arbor to rest and move the guide control lever GC to the left (Fig. 7) or lever 360 to the R position (Fig. 45) in order to condition the feed mechanism for shifting the guide unit B to the right. The operations of placing paper around the second layer of turns are repeated as for the first layer of turns and the pedal T is finally pressed to complete the winding of the third layer of turns which is indicated by the burning of the lamp when the total number of turns is 165 as indicated on dial I (Fig. 35). Therefore the number of turns for the third layer is 50.

Then shift the guide control lever GC to the right or the lever 360 into the L position (Fig. 45) in order to condition the feed mechanism for shifting the wire guide B from right toward left. The operations of applying paper over the third layer of wire turns are repeated as for the preceding layers. Press the pedal T to complete the winding of the fourth and last layer of wire turns; but, before the fourth layer of turns is entirely completed release the pedal T and locate tabs of linen cloth 77 upon the arbor, with the loop end of each tab extending into the winding space and the loose ends of the tabs located over the wires of the fourth layer already wound on the arbor. When placing tabs 77 in this position the arbor is turned so that the tabs 77 will be diametrically opposite the L-shaped holes 73 in strip 10. The reason for so locating the tabs 77 will be more apparent later.

While the tabs 77 are thus located, the arbor 60 is turned in order to wind on a few turns of wire which holds the tabs 77 in position. Then press the pedal T to complete the winding of the fourth turn which is indicated by the burning of the lamp 533. The pointer 515 then points to #210 to indicate that the total number of turns is 210 or that the last layer contains 45 turns. Then the wires W are cut between the wire guide pulleys 171 and the wire tension device pulleys 160 (Fig. 16). These wire ends, marked 78 in Fig. 4, are then each passed through the loop of a tab 77 as shown in Fig. 4 and then each tab is pulled tight as shown in Fig. 5. In this way, the end leads 78 of the coils are permanently located diametrically opposite the L-shaped slots 73.

Press pedals T and KC to cause the knives K to engage the strip 10 while it is rotating. The knives K cut through the strip 10 along the line 79 so that each section of the strip will be provided with a bayonet slot 73x as indicated in Fig. 6a and 6B.

Move tail stock lever 410 toward the right as viewed in Figs. 7 and 39 thereby causing indicator reset lever IR (Fig. 7) or 547 (Fig. 42) to moved toward the left thereby restoring the pointer 515 of indicator I to zero position against the stop 534.

Before the arbor can be removed from the machine, first press on the knee pad 626 which is located at the right-hand side of the operator's right knee. By moving the knee to the right, the pedal 626 (Fig. 55) is moved counter-clockwise to retract the latch 631 from the beam 597, thereby permitting the paper supply unit C to gravitate into the position shown in Fig. 47 thereby providing free access to the front of the arbor.

Then remove the arbor and the completed work thereon from the machine and remove the completed coil units from the arbor. Join inside

lead 61a of each of the primary winding with its adjacent outside lead of a secondary winding marked L1S in Fig. 6B. Thus the two primary leads of the coil are located on opposite sides thereof as shown in Fig. 6B to facilitate making connections with primary terminals located on the non-conducting head of the ignition coil on diametrically opposite sides of the center terminal with which the inside lead of the secondary winding is connected.

While the embodiment of the present invention as herein disclosed, constitutes a preferred form, it is to be understood that other forms might be adopted, all coming within the scope of the claims which follow.

What is claimed is as follows:

1. For use with a coil winding machine having an arbor and means for rotating it, a flat anchoring strip of flexible material adapted to be formed around the arbor and to be retained by the winding of wire thereon and having provisions near each end thereof adapted to cooperate with means provided by machine driven members which support the ends of the arbor and having means for the attachment thereto, before forming the strip around the arbor, of wires leading from supply spools.

2. For use with a coil winding machine having an arbor and machine driven head and tail stock members supporting the arbor, a flat anchoring strip of flexible material adapted to be formed around the arbor and to be retained by the winding of wire thereon and having provisions near each end thereof adapted to cooperate with means provided by machine driven head and tail stock members which support the ends of the arbor and having means for the attachment thereto, before forming the strip around the arbor, of wires leading from supply spools.

3. For use with a coil winding machine having an arbor and a head stock member driving the arbor and a tail stock member driven by the arbor, a flat anchoring strip of flexible material adapted to be formed around the arbor and to be retained by the winding of wire thereon and having provisions near each end thereof adapted to cooperate with means provided by head and tail stock members which support the ends of the arbor and having means for the attachment thereto, before forming the strip around the arbor, of wires leading from supply spools.

4. For use with a coil winding machine having an arbor and machine driven head and tail stock members supporting the arbor, a flat anchoring strip of flexible material adapted to be formed around the arbor and to be retained by the winding of wire thereon and having holes adjacent each end thereof for receiving pins provided by the head and tail stock members whereby said members drive said strip and having means for the attachment thereto, before forming the strip around the arbor, of wires leading from supply spools.

5. For use with a coil winding machine having an arbor and machine driven head and tail stock members supporting the arbor, a flat anchoring strip of flexible material adapted to be formed around the arbor and to be retained by the winding of wire thereon and having provisions near each end thereof adapted to cooperate with means provided by head and tail stock members whereby said members drive said strip and having means for the attachment thereto, before forming the strip around the arbor, of wires leading from supply spools and having a series of spaced round holes intermediate the longer side edges thereof for receiving wires leading from the supply spools.

6. For use with a coil winding machine having an arbor and machine driven head and tail stock members supporting the arbor and having an anchoring strip severing means, an anchoring strip of flexible material adapted to be formed around the arbor and having provisions near each end thereof adapted to cooperate with means on said head and tail stock members whereby said members drive said strip and having means for the attachment thereto of wires leading from supply spools and having a series of elongated holes each located near a means for the attachment of a wire, each elongated hole becoming, when the strip is severed between coil sections at the end of a winding operation, a notch into which the start lead of a coil is passed for the purpose of locating the start lead in predetermined relation to the end lead of the coil.

7. For use with a coil winding machine having an arbor and machine driven head and tail stock members supporting the arbor and having an anchoring strip severing means, an anchoring strip of flexible material adapted to be formed around the arbor and having provisions near each end thereof adapted to cooperate with means on said head and tail stock members whereby said members drive said strip and having means for the attachment thereto of wires leading from supply spools and having a series of L-shaped holes each located near a means for facilitating the attachment of a wire, each L-shaped hole becoming, when the strip is severed between coil sections at the end of a winding operation, a bayonet slot into which the start lead of a coil is passed for the purpose of locating the start lead in predetermined relation to the end lead of the coil.

8. For use with a coil winding machine having an arbor and machine driven head and tail stock members supporting the arbor and having an anchoring strip severing means an anchoring strip of flexible material adapted to be formed around the arbor and having provisions near each end thereof adapted to cooperate with means on said head and tail stock members whereby said members drive said strip and having a series of spaced holes intermediate the longer side edges thereof for receiving wires leading from the supply spools and having a series of L-shaped holes each located near a wire receiving hole, each L-shaped hole becoming, when the strip is severed between the coil sections at the end of a winding operation, a bayonet slot into which the start lead of a coil is passed for the purpose of locating the start lead in predetermined relation to the end lead of the coil.

9. The method of winding a plurality of coils simultaneously upon an arbor upon which coils have already been wound comprising the steps which include mounting the arbor upon a winding machine having machine driven members coaxial with the arbor and located near the ends thereof, connecting with said members an anchoring strip alongside the arbor and capable of being bent around the arbor, attaching to the strip the wires leading from supply spools and then winding turns of wire upon the strip thereby causing it to be maintained around the arbor.

10. The method defined by claim 9 further characterized by the steps of pressing the anchoring strip around the arbor and maintaining the strip in such condition by means of spring clips preparatory to winding wire upon the strip,

winding a few turns upon the shaped strip to maintain it around the arbor, removing the clips, and then completing the winding of the first layer of turns.

5 11. A multiple coil winding machine comprising the combination of a driving spindle, an arbor driven thereby for supporting a plurality of coil sections wound simultaneously thereon, a paper supply unit comprising means for supporting a plurality of stacks of paper strips each furnishing a paper strip to a coil section, means for simultaneously withdrawing single strips of paper from the stacks and means for obstructing the withdrawal of strips from the stacks excepting the top-most strips.

10 12. A multiple coil winding machine comprising the combination of a driving spindle, an arbor driven thereby for supporting a plurality of coil sections wound simultaneously thereon, a paper supply unit comprising a plurality of platforms each for supporting a stack of paper strips, feed rollers each engaged by the top-most strip in a stack, springs each for urging a platform toward a feed roller, means for rotating the feed rollers, and means for obstructing the withdrawal by the feed rollers of all strips from the stacks except the top-most strips.

15 13. A multiple coil winding machine comprising the combination of a driving spindle, an arbor driven thereby for supporting a plurality of coil sections wound simultaneously thereon, a paper supply unit comprising means supporting a plurality of stacks of paper, feed rollers each engaged by the top-most strip in a stack, means for yieldingly urging the stacks against their respective feed rollers, means for obstructing the withdrawal by the feed rollers of all strips from the stacks except the top-most strips and means for rotating the feed rollers to withdraw the top-most strips.

20 14. A multiple coil winding machine comprising the combination of a driving spindle, an arbor driven thereby for supporting a plurality of coil sections wound simultaneously thereon, a paper supply unit comprising means supporting a plurality of stacks of paper, feed rollers each engaged by the top-most strip in a stack, means for yieldingly urging the stacks against their respective feed rollers, means for obstructing the withdrawal by the feed rollers of all strips from the stacks except the top-most strips, a shaft for driving the feed rollers, a pinion supported by and driving said shaft, a gear on the arbor spindle, and means for moving the pinion into mesh with said gear.

25 15. A multiple coil winding machine comprising the combination of a driving spindle, an arbor driven thereby for supporting a plurality of coil sections wound simultaneously thereon, a paper supply unit comprising means supporting a plurality of stacks of paper, feed rollers each engaged by the top-most strip in a stack, means for yieldingly urging the stacks against their respective feed rollers, means for obstructing the withdrawal by the feed rollers of all strips from the stacks except the top-most strips, a shaft for supporting the feed rollers, individual one-way clutches each connecting the shaft with feed rollers while permitting the feed rollers to rotate independently of the shaft, and means for rotating the shaft to operate the feed rollers.

30 16. A multiple coil winding machine comprising the combination of a driving spindle, an arbor driven thereby for supporting a plurality of

coil sections wound simultaneously thereon, means for simultaneously feeding strips of paper to the arbor, one strip for each coil, and means for directing the leading ends of said strips in between the arbor and the wires leading thereto.

17. A multiple coil winding machine comprising the combination of a driving spindle, an arbor driven thereby for supporting a plurality of coil sections wound simultaneously thereon, means for simultaneously feeding strips of paper to the arbor, one strip for each coil, and fingers locatable adjacent the arbor but spaced therefrom and providing means for directing the leading ends of said strips in between the arbor and the wires leading thereto.

18. A multiple coil winding machine comprising the combination of a driving spindle, an arbor driven thereby for supporting a plurality of coil sections wound simultaneously thereon, means for simultaneously feeding strips of paper to the arbor, fingers locatable adjacent the arbor but spaced therefrom and means for directing the leading ends of said strips in between the arbor and the wires leading thereto and means for advancing the fingers into operating position during the application of paper to the arbor and for retracting them from the arbor so as to permit the completion of the winding of a layer of wire turns.

19. A multiple coil winding machine comprising the combination of a driving spindle, an arbor driven thereby for supporting a plurality of coil sections wound simultaneously thereon, means for simultaneously feeding strips of paper to the arbor, a plurality of resilient fingers adapted to be engaged by the paper strips, and apparatus for supporting the fingers and for causing them to move from a normally retracted position to a fully advanced position adjacent the arbor and spaced from the material on the arbor whereby the fingers are located so as to direct the leading ends of the paper strips in between the arbor and the wires leading thereto, and for causing the fingers to move into a certain position intermediate fully advanced and fully retracted positions and, when in said intermediate position, to bear resiliently against the paper strips as they are being wound upon the arbor.

20. A multiple coil winding machine comprising the combination of a driving spindle, an arbor driven thereby for supporting a plurality of coil sections wound simultaneously thereon, means for simultaneously feeding strips of paper to the arbor, a plurality of resilient fingers adapted to be engaged by the paper strips, means for moving the fingers lengthwise from a position normally retracted from the arbor to a fully advanced position adjacent the arbor, and means cooperating with the finger moving means for causing the fingers to be located in positions spaced from the material on the arbor when the fingers are fully advanced whereby the fingers are in position for directing the leading ends of the paper strips in between the arbor and the wires leading thereto, said last named means operating, when the first named means locates the fingers in a certain position intermediate fully advanced and fully retracted positions, to locate the fingers so that they resiliently bear against the paper strips as they are moved about the arbor.

21. A multiple coil winding machine comprising the combination of a driving spindle, an ar-

bor driven thereby for supporting a plurality of coil sections wound simultaneously thereon, means for simultaneously feeding strips of paper to the arbor, a plurality of resilient fingers adapted to be engaged by the paper strips, finger bar members each supporting a finger at one end, means attached to the other ends of the bar members for moving the fingers lengthwise from a position normally retracted from the

10 arbor to a fully advanced position adjacent the arbor, and a member for supporting each bar member intermediate its ends, each bar member and its supporting member providing camming means whereby the bar member will be so positioned that when its finger is in fully advanced position, said finger will be spaced from the material on the arbor whereby the finger will be in position for directing the leading end of a paper strip in between the arbor and a wire leading thereto, said camming means operating,

20 when the bar member is in a certain position intermediate fully advanced and fully retracted position, to cause the finger to bear resiliently against the paper strip while it is being wound about the arbor.

22. A multiple coil winding machine comprising the combination of a driving spindle, an arbor driven thereby for supporting a plurality of coil sections wound simultaneously thereon, means for simultaneously feeding strips of paper to the arbor, a plurality of resilient fingers adapted to be engaged by the paper strips, finger bar members each supporting a finger at one end, means attached to the other ends of the bar members for moving the fingers lengthwise from a position normally retracted from the arbor to a fully advanced position adjacent the arbor, a roller for engaging the underside of each bar member for supporting the bar member intermediate its ends, the bar member having a roller engaging surface so shaped that, when the finger is in fully advanced position, the finger will be spaced from the material on the arbor whereby the finger will be in position for directing the leading end of a paper strip in between the arbor and a wire leading thereto, said roller engaging surface providing a notch for receiving the roller whereby, when the finger is in a certain position intermediate fully advanced and fully retracted position, the bar will

30 so move laterally, that the finger will be caused to bear resiliently against the paper strip while it is being wound about the arbor.

23. In a coil winding machine, the combination with a rotatable arbor upon which a coil of wire is wound, of means for supporting a stack of paper strips with their end edges facing the arbor, means frictionally engaging the top-most strip to cause it to move from the stack toward the arbor, and means engaging the leading end edges of those strips under the top-most strip to prevent them from being dragged from the stack due to frictional engagement of the top-most strip with the under-lying strip.

24. In a coil winding machine, the combination with a rotatable arbor upon which a coil of wire is wound, of means for supporting a stack of paper strips with their end edges facing the arbor, means frictionally engaging the top-most strip to cause it to move from the stack toward the arbor, and means engaging the leading end edges of those strips under the top-most strip to prevent them from being dragged from the stack due to frictional engagement of the top-

most strip with the under-lying strip, said last named means comprising a plate having a surface engaged by the leading end edges of the strips and inclined with respect to the stack so as to permit relative displacement of certain strips in the direction of movement of the top-most strip from the stack, said surface merging with a second surface inclined with respect to the first surface so as to define a shallow groove in which the leading end edge of the strip next to the top-most strip is caught and further movement of the strip next to the top-most strip is resisted by reason of engagement of said under-lying strip with the second mentioned surface of the plate.

25. In a coil winding machine the combination with a rotatable arbor upon which a coil of wire is wound of means for moving a strip of paper toward the arbor, a finger which is normally retracted from the arbor to permit the winding of a complete layer of wire thereon, and means for moving the finger adjacent the arbor and spaced therefrom in order to direct the moving strip of paper in between the arbor and a wire leading thereto from a supply spool, and for moving the finger against the paper strip on the arbor while it is being wound thereon.

26. A coil winding machine comprising an arbor, means for rotating the arbor, a paper supply unit for supplying a strip of paper to the arbor, pinion driven means for operating the unit, said pinion being carried by the unit and adapted to be engaged by a gear driven by the arbor rotating means, and means for moving the unit from a normally retracted position into operating position adjacent the arbor and for moving the pinion into mesh with said gear.

27. A coil winding machine comprising an arbor, means for rotating the arbor, a paper supply unit for supplying a strip of paper to the arbor, pinion means for operating the unit, said pinion being carried by the unit and adapted to engage a gear driven by the arbor rotating means, a finger for directing the strip of paper in between the arbor and a wire leading thereto from a supply spool, and means for moving the unit from a normally retracted position adjacent the arbor and for moving the pinion into mesh with said gear and for moving the finger from a normally retracted position into operating position.

28. A coil winding machine comprising an arbor, means for rotating the arbor, a paper supply unit for supplying a strip of paper to the arbor, pinion means for operating the unit, said pinion being carried by the unit and adapted to engage a gear driven by the arbor rotating means, a finger having a normally fully retracted position, a fully advanced position in which the finger operates to direct the strip of paper in between the arbor and a wire leading thereto from a supply spool and having an intermediate position in which the finger bears against the paper strip while it is wound upon the arbor, and means for moving the unit from a normally retracted position into operating position adjacent the arbor and for moving the pinion into mesh with said gear and for moving the finger into its operating position.

29. A coil winding machine comprising an arbor, means for rotating the arbor, a paper supply unit for supplying a strip of paper to the arbor, pinion means for operating the unit, said pinion being carried by the unit and adapted to engage a gear driven by the arbor rotating

means, a finger for directing the strip of paper in between the arbor and a wire leading thereto from a supply spool, and means for moving the unit from a normally retracted position into operating position adjacent the arbor and for moving the pinion into mesh with said gear and for moving the finger from a normally retracted position into operating position and for returning the finger to normal position and for permitting movement of unit to an intermediate position in which its pinion is demeshed from said gear, and means for retaining the unit in said intermediate position while permitting the first named means to return the finger to normal position.

30. A coil winding machine comprising an arbor, means for rotating the arbor, a paper supply unit for supplying a strip of paper to the arbor, said unit being normally located a substantial distance below the arbor to permit removal of the arbor from the machine, pinion driven means for operating the unit, said pinion being carried by the unit and adapted to engage a gear driven by the arbor rotating means, means for moving the unit from normal to operating position adjacent the arbor and for moving the pinion into mesh with said gear, a latch which permits full upward movement of the unit but which operates, during downward movement of the unit to retain the unit against the action of gravity in an intermediate position in which the pinion is demeshed from the gear, and means for retracting the latch to permit the unit to descend to normal position.

35. 31. A coil winding machine comprising an arbor, means for rotating the arbor, a paper supply unit for supplying a strip of paper to the arbor, said unit being normally located a substantial distance below the arbor to permit removal of the arbor from the machine, pinion driven means for operating the unit, said pinion being carried by the unit and adapted to engage a gear driven by the arbor rotating means, a finger having a normally fully retracted position, a fully advanced position in which the finger operates to direct the strip of paper in between the arbor and a wire leading thereto from a supply spool and having an intermediate position in which the finger bears against the paper strip while it is wound upon the arbor, means for moving the finger from normal to fully advanced position and for concurrently moving the unit from normal to fully elevated position in which the pinion of the unit meshes with the gear, and for moving the finger into said intermediate position and permitting the unit to gravitate to an intermediate position in which the pinion is demeshed from the gear, a latch which permits full upward movement of the unit but which operates, during downward movement of the unit to retain the unit against the action of gravity in said intermediate position, and means for retracting the latch to permit the unit to descend to normal position.

32. A coil winding machine comprising a rotatable arbor, means for moving a strip of paper toward the arbor, a finger having a normal position fully retracted from the arbor, and having a fully advanced position in which the finger is located adjacent the arbor but is spaced therefrom for the purpose of directing the movement of the paper strip in between the arbor and a wire leading thereto from a supply spool and having an intermediate position in which the

finger rests upon the strip while it is being wound upon the arbor, a bar carrying the finger, a support for the bar upon which the bar rests during movement thereof, cooperating means provided by the bar and support for permitting bar to gravitate to a lower position in order to locate the finger in its intermediate position, pedal operated means for moving the bar in order to move the finger from fully retracted to fully advanced position, a main spring for restoring the pedal operated means to normal position, and a booster spring operated means for assisting the main spring to operate through said pedal operated means to elevate the finger bar during movement of the finger from its intermediate position to its fully retracted position, said booster means including an auxiliary spring in which energy is stored during movement of the finger from normal toward operating position.

33. A coil winding machine comprising a power driven shaft, an arbor driving spindle, means for causing torque to be transmitted from the shaft to the spindle in proportion to the amount of movement, from normal, of an operating lever, said means comprising a lever operated valve controlling the pressure of a pressure fluid in accordance with the position of the operating lever, a force transmitting mechanism actuated by the pressure fluid, and friction plate clutch actuated by the force transmitting mechanism and adjusted to transmit torque between the shaft and spindle in proportion to the value of the pressure of the pressure fluid and, therefore, substantially in proportion to movement of the operating lever.

34. A coil winding machine comprising means for driving a rotatable arbor upon which layers of wire turns are wound, a wire guide mounted for movement parallel to the arbor, means for moving the wire guide comprising oppositely feeding feed screws, a member connected with the wire guide and carrying nut segments cooperating respectively with said feed screws, means for shifting the member from one screw to the other, means for locking the wire guide against movement when neither feed screw is engaged by a nut segment, and means for retracting said locking means when a feed screw is being engaged by a nut segment.

35. A coil winding machine comprising means for driving a rotatable arbor upon which layers of wire turns are wound, a wire guide mounted for movement parallel to the arbor, means for moving the wire guide comprising oppositely feeding feed screws, a member connected with the wire guide and carrying nut segments cooperating respectively with said feed screws, means for shifting the member from one screw to the other, means for locking the wire guide against movement when either feed screw is engaged by a nut segment, and means operated by said member shifting means for retracting said locking means when a feed screw is being engaged by a nut segment.

36. A coil winding machine comprising means for driving a rotatable arbor upon which layers of wire turns are wound, a wire guide mounted for movement parallel to the arbor, means for moving the wire guide comprising oppositely feeding feed screws, a member connected with the wire guide and carrying nut segments cooperating respectively with said feed screws, means for shifting the member from one screw to the other, means for locking the wire guide against

movement when neither feed screw is engaged by a nut segment, means for retracting said locking means when a feed screw is being engaged by a nut segment, and other means for 5 retracting the locking means although the member is out of engagement with a feed screw in order to release the wire guide for movement to the normal or start position.

37. A coil winding machine comprising means 10 for driving a rotatable arbor upon which layers of wire turns are wound, a wire guide mounted for movement parallel to the arbor, means for moving the wire guide comprising oppositely feeding feed screws, a member connected with the wire guide and carrying nut segments cooperating, respectively, with said feed screws, means for shifting the member from one screw to the other, means for locking the wire guide against movement when neither feed screw is engaged by a nut segment, means operated by said member shifting means for retracting the locking means when a feed screw is being engaged by a nut segment, and other means for retracting the locking means although the member is out of engagement with a feed screw in order to release the wire guide for movement to the normal or start position.

38. A coil winding machine comprising means 30 for driving a rotatable arbor upon which layers of wire turns are wound, a wire guide mounted for movement parallel to the arbor, means for moving the wire guide comprising oppositely feeding feed screws, a member connected with the wire guide and carrying nut segments cooperating, respectively, with said feed screws, means for shifting the member from one screw to the other, means for locking the wire guide against movement when neither feed screw is engaged by a nut segment, means for retracting said locking means when a feed screw is being engaged by a nut segment, and a manually operable lever for operating the member shifting means and the lock retracting means.

39. A coil winding machine comprising means 45 for driving a rotatable arbor upon which layers of wire turns are wound, a wire guide mounted for movement parallel to the arbor, means for moving the wire guide comprising oppositely feeding feed screws, a member connected with the wire guide and carrying nut segments cooperating, respectively, with said feed screws, means for shifting the member from one screw to the other, means for locking the wire guide against movement when neither feed screw is engaged by a nut segment, means for retracting said locking means when a feed screw is being engaged by a nut segment, a manually operable lever for operating the member shifting means and the lock retracting means, and other means operated by a hand grip lever mounted on said first mentioned manually operable lever for retracting the locking means although the member is out of engagement with a feed screw in order to release the wire guide for movement to the normal or start position.

40. A coil winding machine comprising means 60 for driving a rotatable arbor upon which layers of wire turns are wound, a wire guide mounted for movement parallel to the arbor, a rod connected with said wire guide and mounted for movement parallel to the arbor, a nut carrier pivotally mounted on said rod and connected therewith to impart endwise movement to the rod, oppositely feeding feed screws, nut segments provided by said nut carrier and cooperating re-

spectively with said feed screws, means for locking the rod against endwise movement, means for shifting the nut carrier to cause a nut segment to move into and out of engagement with a feed screw, and means operated by the nut carrier moving means for retracting the rod locking means when a nut segment is engaging the feed screw.

41. A coil winding machine comprising means for driving a rotatable arbor upon which layers of wire turns are wound, a wire guide mounted for movement parallel to the arbor, a rod connected with said wire guide and mounted for movement parallel to the arbor, a nut carrier pivotally mounted on said rod and connected therewith to impart endwise movement to the rod, oppositely feeding feed screws, nut segments provided by said nut carrier and cooperating respectively with said feed screws, means for locking the rod against endwise movement, means for shifting the nut carrier to cause a nut segment to move into and out of engagement with a feed screw, means operated by the nut carrier moving means for retracting the rod locking means when a nut segment is engaging a feed screw and other means independently of the nut carrier moving means for retracting the rod locking means although neither feed screw is engaged by a nut segment.

42. A coil winding machine comprising means for driving a rotatable arbor upon which layers of wire turns are wound, a wire guide mounted for movement parallel to the arbor, a rod connected with said wire guide and mounted for movement parallel to the arbor, a nut carrier pivotally mounted on said rod and connected therewith to impart endwise movement to the rod, oppositely feeding feed screws, nut segments provided by said nut carrier and cooperating respectively with said feed screws, means for locking the rod against endwise movement including a locking nut for engaging a screw threaded portion of said rod, a tube attached to the rod and surrounding the screw threaded portion thereof except for a longitudinally elongated opening in the tube into which the locking nut may extend to engage the screw-threaded portion of said rod, the side edges of the tube, which define the elongated opening therein, being engageable with the locking nut to move the nut out of engagement with the threaded portion of said rod, and a common means for shifting the nut carrier and for turning the rod and tube in order to retract the nut from locking engagement with the rod when a nut segment engages a feed screw.

43. A coil winding machine comprising means for driving a rotatable arbor upon which layers of wire turns are wound, a wire guide mounted for movement parallel to the arbor, a rod connected with said wire guide and mounted for movement parallel to the arbor, a nut carrier pivotally mounted on said rod and connected therewith to impart endwise movement to the rod, oppositely feeding feed screws, nut segments provided by said nut carrier and cooperating respectively with said feed screws, means for locking the rod against endwise movement including a locking nut for engaging a screw threaded portion of said rod, a tube attached to the rod and surrounding the screw threaded portion thereof except for a longitudinally elongated opening in the tube into which the locking nut may extend to engage the screw-threaded portion of said rod, the side edges of the tube, which define the elongated opening therein, being engageable with the

locking nut to move the nut out of engagement with the threaded portion of said rod, a common means for shifting the nut carrier and for turning the rod and tube in order to retract the nut from locking engagement with the rod when a nut segment engages a feed screw and other means independent of said common means for retracting the rod locking nut although neither feed screw is engaged by a nut segment.

44. A coil winding machine comprising means for driving a rotatable arbor upon which layers of wire turns are wound, a wire guide mounted for movement parallel to the arbor, a rotatable rod mounted for movement parallel to the arbor, a shiftable nut carrier connected with said rod to impart endwise movement to the rod, oppositely feeding feed screws, nut segments provided by said nut carrier and cooperating respectively with said feed screws, means for shifting the nut carrier and for rotating the rod, means for locking the rod against endwise movement while neither of the feed screws is engaged by a nut segment, means responding to a rotation of the rod for retracting the rod locking means when a nut segment is engaging a feed screw, and means for connecting the rod with the wire guide so as to transmit motion from the nut carrier to the wire guide parallel to the arbor and also for causing the wire guide to move parallel to the arbor in response to rotation of the rod.

45. A coil winding machine comprising means for driving a rotatable arbor upon which layers of wire turns are wound, a wire guide, a wire guide supporting tube mounted for movement parallel to the arbor, a rotatable rod mounted partly within said wire guide supporting tube, means connecting the rod with the tube whereby endwise motion is transmitted from rod to the tube and whereby the tube is caused to move endwise in response to rotation of the rod, a shiftable nut carrier connected with said rod to impart endwise movement to the rod, oppositely feeding feed screws, nut segments provided by said nut carrier and cooperating respectively with said feed screws, means for shifting the nut carrier and for rotating the rod, means for locking the rod against endwise movement while neither of the feed screws is engaged by a nut segment, means responding to a rotation of the rod for retracting the rod locking means when a nut segment is engaging a feed screw.

46. A coil winding machine comprising means for driving a rotatable arbor upon which layers of wire turns are wound, a wire guide, a wire guide supporting tube mounted for movement parallel to the arbor, a rotatable rod mounted partly within said wire guide supporting tube, means connecting the rod with the tube whereby endwise motion is transmitted from rod to the tube and whereby the tube is caused to move endwise in response to rotation of the rod, said connecting means comprising a screw member attached to the rod and located within the tube and a member attached to the tube and cooperating with said screw member, a shiftable nut carrier connected with said rod to impart endwise movement to the rod, oppositely feeding feed screws, nut segments provided by said nut carrier and cooperating respectively with said feed screws, means for shifting the nut carrier and for rotating the rod, means for locking the rod against endwise movement while neither of the feed screws is engaged by a nut segment, means responding to a rotation of the rod for retract-

ing the rod locking means when a nut segment is engaging a feed screw.

47. A coil winding machine comprising means for driving a rotatable arbor upon which layers of wire turns are wound, a wire guide, a wire guide supporting tube mounted for movement parallel to the arbor, a rotatable rod having one end located within said wire guide supporting tube and provided at that end with a screw member of relative coarse pitch, a member carried by the wire guide supporting tube and cooperating with said screw whereby endwise motion is transmitted by the rod to the tube and whereby the tube is caused to move endwise in response to rotation of the rod, said rod provided at its other end with a screw of finer pitch, a locking nut member cooperating with said last named screw to lock the rod against endwise movement, oppositely feeding feed screws, nut segments respectively engaging said feed screw, a nut carrier supporting the nut segments and pivotally mounted on said rod and operatively connected therewith so that the carrier imparts endwise movement to the rod, means for shifting the nut carrier and for rotating the rod, and means responsive to rotation of the rod for retracting the locking nut from the fine threaded end of the rod when a nut segment engages a feed screw.

48. A coil winding machine comprising means for driving a rotatable arbor upon which layers of wire turns are being wound, a wire guide mounted for movement parallel to the arbor, oppositely feeding feed screws, nut segments respectively engaging said feed screws, a shiftable nut segment carrier connected with the wire guide, means for resiliently urging the nut segment carrier in either direction to press a nut segment against its feed screw, said means comprising interconnected levers movable in opposite directions, one of the levers being connected to the nut segment and a spring connecting remote ends of the levers for biasing the levers in a direction dependent upon the relation of the center line of action of the spring to the pivotal axes of the levers, and means controlled by the operator for shifting one of the levers in order to move the center line of action of the spring from one side of the lever pivots to the other.

49. A coil winding machine comprising means for driving a rotatable arbor upon which layers of wire turns are being wound, a wire guide mounted for movement parallel to the arbor, oppositely feeding feed screws, nut segments respectively engaging said feed screws, a shiftable nut segment carrier connected with the wire guide, means normally locking the wire guide against endwise movement when a feed screw is not engaged by a nut segment, means responsive to the shifting to the nut segment carrier for retracting the locking means when a nut segment is engaging a feed screw, means for resiliently urging the nut segment carrier in either direction to press a nut segment against its feed screw, said means comprising interconnected levers movable in opposite directions, one of the levers being connected to the nut segment and a spring connecting remote ends of the levers for biasing the levers in a direction dependent upon the relation of the center line of action of the spring to the pivotal axes of the levers, and means controlled by the operator for shifting one of the levers in order to move the center line of action of the spring from one side of the lever pivots to the other.

50. A coil winding machine comprising means

for rotating an arbor upon which layers of wire coils are wound, a bracket carrying a wire guide, means for causing the bracket to move parallel to the arbor, a wire tension device mounted on said bracket and comprising three guide pulleys which are so located as to place an S-bend in the wire, a plate pivoted about the axis of the intermediate pulley and carrying another of the pulleys, and means for securing the plate to the bracket in the desired position of adjustment.

51. A coil winding machine comprising means for rotating an arbor upon which layers of wire coils are wound, an arbor revolution counter including a shaft driven by the arbor rotating means, a rotatable pointer frictionally connected with the shaft, a stationary dial cooperating with pointer to indicate revolutions of the arbor, a tail-stock supporting the arbor and retractable from the arbor to release it, and means responsive to retraction of the tail-stock from the arbor for returning the pointer to zero position on the dial.

52. A coil winding machine comprising means for rotating an arbor upon which layers of wire coils are wound, an arbor revolution counter including a shaft driven by the arbor rotating means, a rotatable pointer frictionally connected with the shaft, a stationary dial cooperating with pointer to indicate revolutions of the arbor, a plate movable with the pointer and carrying pins adjustably mounted thereon, and a switch operated by a pin at the end of the winding of a layer of wire, and a signal device controlled by said switch.

53. A coil winding machine comprising means for rotating an arbor upon which layers of wire coils are wound, and including a spindle upon which an oil seal frictionally bears, a hand wheel for rotating the spindle, means mounting the hand wheel upon the spindle and for thermally insulating the hand wheel from the spindle and means for air cooling the hand wheel.

54. A coil winding machine comprising means for rotating an arbor upon which layers of wire coils are wound, and means for supplying wire to the arbor comprising a support upon which a wire spool rests by gravity, a tubular member carried by the support and received by the hub of the spool, and a wire unreeling device supported by the tubular member and comprising a rod extending through said member to a location below the support, means located underside the support for locking said rod against rotary and upward movement, a ball bearing having its inner race supported by said rod, a wire unreeling arm supported by the outer race of said ball bearing, a friction brake including a friction member rotating with said unreeling arm and a plate slidably on said rod and held from rotating thereby, and means for adjusting the pressure between said brake members.

55. For use with a coil winding machine having an arbor and means for rotating it, a flat anchoring strip of flexible material apertured adjacent its ends adapted to cooperate with machine driven members provided adjacent the ends of the arbor, said strip having a series of openings intermediate its ends through which a series of wires pass and having a series of notches along one longitudinal edge thereof to receive the ends of the wires from the underside of the strip which are bent against the underside of the strip to anchor the wires, said strip with

the wires so anchored being adapted to be wrapped around the arbor.

56. For use with a coil winding machine having an arbor and means for rotating it, a flat anchoring strip of flexible material apertured adjacent its ends adapted to cooperate with machine driven members provided adjacent the ends of the arbor, said strip having provisions

intermediate its longitudinal edges through which a series of wire ends may pass which are bent over one of the longitudinal edges and against the upper side of the strip to anchor the wires, said strip with the wires so anchored being adapted to be wrapped around the arbor.
